ABSTRACT

A method for assembling partition strips slit inwardly from one edge into inner pack assemblies, wherein a group of partition strips adapted to lie parallel and extend in one direction in the pack assembly are gathered in parallel, vertically spaced, longitudinally staggered relation and at an incline to the horizontal with their edges at the slits spread vertically, and another group of partition strips adapted to lie parallel and extend at an angle to the direction of the first group in the pack assembly are gathered in parallel, vertically spaced, longitudinally staggered relation and horizontal at a position confronting the first group, and the two groups are brought together in interlocking relation. Machines for carrying out the method are disclosed with magazines for holding supplies of the partition strips of the two groups, and having means to eject strips from the magazines, transport them to the opposed, confronting position, and leave them in the arrangements set out in the method. Additional means moves one group toward the other to assemble the inner pack. Several embodiments of the invention are disclosed, illustrating various arrangements of magazines and various means for operating the gathering mechanisms.

This technical drawing illustrates a mechanical assembly, likely a component of a larger machine. The drawing is annotated with numerous part numbers, some of which are grouped together with a leader line. The assembly includes several circular components, possibly bearings or pulleys, and various structural elements. The part numbers are as follows:

- 348, 349, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385.

Two large leader lines are present, one on the left side and one on the right side, each pointing to a group of part numbers. The leader line on the left points to the group: 348, 349, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385. The leader line on the right points to the group: 348, 349, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385.

INNER PACK ASSEMBLY MACHINE

BACKGROUND OF THE INVENTION

This invention relates to a method for assembling inner packs and to inner pack-assembling machines, and more particularly to machines for gathering and assembling precut partition, or divider, strips into inner packs for containers.

So-called inner packs, or inner pack assemblies, are used in cartons, crates, or other containers to subdivide, or partition, the container space into a plurality of smaller spaces, each to hold an article, usually breakable, and retain the several articles in separated relation. Normally, the assembly consists of a plurality of partition strips in spaced, parallel relation extending in one direction, and a second plurality of spaced, parallel partition strips extending at right angles to the first plurality to form a series of rows of rectangular compartments. The strips of the two groups are slit, or notched, inwardly along one edge, and strips of the two groups are interengaged at their notches, or slits, to releasably secure the partitions in assembled relation. As the assembled strips define a plurality of identical parallelograms, the pack can be collapsed into a substantially flat, compact package for shipment, or storage.

The automatic and relatively high-speed assembly of inner packs has presented many problems in the past, and the present invention is designed to solve these.

SUMMARY OF THE INVENTION

The principal object of the present invention is to provide a method by which pluralities, or groups of partition strips can be gathered and positioned to facilitate assembly, and a machine which will automatically gather two pluralities of precut partition, or divider, strips, bring the two pluralities into juxtaposition, assemble them, and discharge the assembled pack.

A more specific object is to provide such a method wherein the strips of one plurality are arranged in parallel, spaced relation, with the strips progressively staggered in one direction, while the strips of the second plurality are similarly arranged but held at a small angle relative to the first to facilitate assembly.

An additional object is to provide a method whereby the sides of the slits of one group of partition strips are spread vertically to enable the strips of the other group to be easily inserted to complete assembly.

Yet another object of the invention is the provision of a machine which will arrange the strips of one group in parallel, spaced relation, with the strips progressively staggered in one direction, and will arrange the strips of a second group in similar fashion, but a small angle relative to the first.

Another object is the provision of means to separate the edges of the notches of the strips of one plurality to provide for easy entry of the strips of the other plurality at assembly.

A further object is to provide a machine of this type having improved means for ejecting precut strips from a source of supply.

Still another object of the invention is to provide several alternate means for gathering pluralities of strips and bringing the pluralities into juxtaposition for assembly.

Other objects of the invention will appear from the following detailed description of several embodiments thereof, when taken in conjunction with the drawings which accompany, and form a part of, this specification.

BRIEF DESCRIPTION OF THE DRAWINGS

FIGS. 1-A and 1-B combined, illustrate a top plan view of a machine for assembling inner packs, embodying the principles of the present invention;

FIG. 2 is a divided view illustrating the machine in side elevation;

FIG. 3 is an end view of the machine, viewed from the discharge end;

FIG. 4-A and 4-B, together, constitute a horizontal section taken on the line 4—4 of FIG. 2, showing the underside of the table of the machine;

FIG. 5-A is a perspective view showing the position of the strips of the two pluralities when ready for assembly;

FIG. 5-B illustrates the assembled inner pack;

FIG. 6 is a vertical, transverse section through the machine, taken on line 6—6 of FIG. 2;

FIG. 7 is a divided, longitudinal section through the machine, taken on the line 7—7 of FIG. 6, illustrating the means for advancing the strips of one group to a position for assembly;

FIG. 8 is a divided longitudinal section, taken on the line 8—8 of FIG. 6, showing the means for advancing strips of the other group to a position for assembly;

FIG. 9 is a divided, longitudinal section, taken on the line 9—9 of FIG. 6, showing an elevating means for gathering strips of one plurality in vertically separated position and aligning them with guides for movement into position for subsequent assembly;

FIG. 10 is a transverse section through the machine of the assembly position, and is taken on the line 10—10 of FIG. 2;

FIG. 11 is a transverse vertical section through the machine at one strip-gathering position, and is taken substantially on the line 11—11 of FIG. 1-B;

FIG. 12 is a vertical section through one of the strip feed magazines and a strip-controlling means, taken on the line 12—12 of FIG. 11;

FIG. 13 is an enlarged, fragmentary, top plan view illustrating feed control mechanism at one strip magazine;

FIG. 14 is a similar view to FIG. 13, but with the parts of the control mechanism moved to a different position;

FIG. 15 is an enlarged, fragmentary, side elevation of strip feed control means cooperating with the structure shown in FIGS. 13 and 14;

FIG. 16 is a vertical section taken on the line 16—16 of FIG. 15, with the parts shown in full lines ready for operation, and in dotted lines in inoperative position;

FIG. 17 is a fragmentary, horizontal section, taken on the line 17—17 of FIG. 15;

FIG. 18 is a view similar to FIG. 16, but with the parts shown in full lines in operative position;

FIG. 19 is a perspective view of part of the mechanism for advancing one of the groups of strips to the assembly position;

FIG. 20 is an enlarged, vertical section through a portion of the strip-advancing means shown in FIG. 19, and is taken on line 20—20 of FIG. 19;

FIG. 21 is an exploded perspective view of the drive shaft and cranks and cams for operating the various mechanisms of the machine;

FIG. 22 is a top plan view of the major portion of a machine of slightly modified construction;

FIG. 23 is an enlarged, side elevation of the structure shown in FIG. 22;

FIG. 24 is an end elevation of the modified machine, as seen from the discharge end of the machine;

FIG. 25 is a view of the underside of the table of the second form of the invention;

FIG. 26 is a transverse section, taken on the line 26—26 of FIG. 22;

FIG. 27 is a vertical, longitudinal section, taken on the line 27—27 of FIG. 26;

FIG. 28 is a vertical, longitudinal section, taken on the line 28—28 of FIG. 24;

FIG. 29 is a partial, vertical, traverse section, taken on the line 29—29 of FIG. 23;

FIG. 30 is a horizontal section through the short partition strip magazine and its feeding mechanism, taken on the line 30—30 of FIG. 23, with the parts shown in position ready to feed a strip from the magazine;

FIG. 31 is a view similar to FIG. 30, but with the mechanism in position to move the bottom strip in the magazine transversely of the machine prior to longitudinal ejection of the strip from the magazine;

FIG. 32 is a view similar to FIGS. 30 and 31, but with parts for moving the bottom strip being shown in inoperative position for retraction of the gathering bar;

FIG. 33 is an enlarged, cross section through the short partition strip magazine taken substantially on the line 33—33 of FIG. 28;

FIGS. 34-A and 34-B, together, illustrate in side elevation a third form of the pack-assembling machine;

FIG. 35-A and FIG. 35-B, together, show the machine in top elevation;

FIG. 36 is an end elevation of the third form;

FIG. 37 is a transverse section through the machine at the assembly position, and is taken on the line 37—37 of FIG. 34-A;

FIG. 38 is a longitudinal section, taken on the line 38—38 of FIG. 37;

FIG. 39 is a horizontal section looking at the underside of the machine at the assembly position, and is taken in line 39—39 of FIG. 38;

FIG. 40 is a vertical transverse section at one of the feed magazines, and is taken on the line 40—40 of FIG. 34-A;

FIG. 41 is a partial, vertical section through the magazine and feed mechanism, taken on the line 41—41 of FIG. 40;

FIG. 42 is another vertical section illustrating a part of the partition strip feed mechanism and control, and is taken on the line 42—42 of FIG. 40;

FIG. 43 is a vertical, longitudinal section through the magazine for short partition strips, and is taken on the line 43—43 of FIG. 40;

FIG. 44 is a fragmentary vertical section illustrating a portion of the feed mechanism, taken on the line 44—44 of FIG. 34-A;

FIG. 45 is another section illustrating the mechanism shown in FIG. 44, and is taken on the line 45—45 of FIG. 44;

FIG. 46 is a diagrammatic view of the electrical circuit for controlling the third form of the machine;

FIG. 47 is a top plan view of a fourth embodiment of the invention;

FIG. 48 is an end view of the machine shown in FIG. 47, and is shown on an enlarged scale;

FIGS. 49-A and 49-B, together, illustrate the fourth form of the invention in side elevation;

FIG. 50 is a partial, transverse section through the machine, taken on the line 50—50 of FIG. 49-A;

FIG. 51 is a partial, longitudinal section through the machine, taken on the line 51—51 of FIG. 48; and

FIG. 52 is a diagrammatic view of the electrical control system for the fourth embodiment of the machine.

DESCRIPTION OF THE PREFERRED EMBODIMENTS

Before describing the several embodiments of the machine, the inner pack assembly produced by the machine, and the component parts of the pack, will be described to facilitate an understanding of the machine and its operation. The components of the assembly, and the assembled pack, are shown in FIGS. 5-A and 5-B, respectively.

For purposes of disclosure, the inner pack assembly 1 will be described as composed of a group of longitudinal partition strips 2 and a group of transverse partition strips 3. While the longitudinal strips 2 are shown as longer and fewer in number than transverse strips 3, the relative length and numbers of the strips of the two groups will vary in accordance with the size, shape and end use of the container to receive the pack. In this disclosure, the pack will be described as having three longitudinal strips 2 and five shorter, transverse strips 3.

Strips 2 are slit inwardly from one long edge to approximately one-half the depth of the strip to provide five open end slits, or notches, 4, equally spaced from one another and from the end edges of the strips. Strips 3 are similarly slit to form three open end slits, or notches, 5. The strips are assembled by interfitting the respective notches of the transverse and longitudinal strips, so that a notch of one member embraces the sidewall of another along a continuation of the slit in the other. This is a common, and well-known, assembly of partitions which are to lie at right angles to one another when in a

container in position for use. This type of assembly also permits the pack to collapse for shipment, as each compartment is a parallelogram. The collapsing faculty of the pack is utilized to facilitate assembly of the strips in the method and in the machine of the present invention.

The method of assembling inner packs forming part of the present invention includes a first step the gathering together of a predetermined number of strips 3 from a source of supply, and arranging the gathered strips in a group at an assembly point. The strips are arranged at an angle to the horizontal, and in vertically spaced, parallel, longitudinally staggered relation, with the edges of the slits, or notches, in the strips being vertically spread to form entrance throats for strips 2 at assembly. As a second step, a predetermined number of strips 2 are gathered from one or more sources of supply and positioned as a group in opposed and confronting relation to the first group. The strips 2 of the gathered group are arranged in horizontal, parallel position, with the strips being vertically spaced and longitudinally staggered to the same degree as the strips 3 of the first group. This presents the two groups of strips in horizontally spaced relation with the strips occupying positions for interlocking engagement when the strips of the two groups are brought together. As a final step, groups are brought together by horizontal movement, with the strips 2 moving freely into the converging throats formed by the spread slit sides of the strips 3.

While the method is described by allocating specific positions of the strips 2 and 3 of two groups, the positions of the groups may be reversed, with the strips 2 being angularly positioned and the slit edges spread, while the strips 3 may be horizontal.

Although several embodiments of the machine are disclosed herein, all perform the above method and contain means to gather one group of slit, insert partition strips in vertically spaced, parallel relation, with the strips progressively staggered relative to one another, together with means to gather a second group of slit, insert partition strips in inclined, vertically spaced, parallel relation with the several tabs formed between the slits held generally horizontal, and in vertically spaced, longitudinally stepped position, with means to move the two gathered groups together to cause interfitting of the slit, insert partition strips into an inner pack assembly, and finally, means to cause delivery of the assembly from the machine.

Referring now in detail to that form of the invention illustrated in FIGS. 1 through 21, there is shown a preferred embodiment of a machine for assembling inner packs for containers. The machine includes, essentially, a base 6 of any suitable construction, on which is mounted a frame 7 supporting a table 8. Partition supply magazines 9 and 10 are carried on the table.

Frame 7 consists of a pair of longitudinally extending, transversely spaced sideplates 11 and 12, connected at their end by transversely extending end plates 13 and 14. This structure supports the table 8, and carries certain mounting brackets which will be described in connection with the mechanisms they support.

Magazine 9 contains a supply of short, transverse partition strips 3, and is carried, in part, by sideplate 11 of the frame and, in part, by an adjustable rail 15 forming part of the table 8. A sidewall 16 of the magazine is mounted on rail 15 by means of brackets 17, and, as rail 15 is movable, as will be described, the sidewall 16 of the machine can be shifted to allow for adjustment to accommodate strips of different depth. A fixed sidewall 18 is permanently mounted on the sideplate 11. Movable sidewall 16 carries a backplate 19, that has inwardly projecting ledges 20 at its bottom to support one end of the bottom, short, transverse strip 3 of a stacked supply of strips 3 in the magazine. The front 21 of the magazine is open to permit strips to be ejected.

A supply of strips in magazine 9 is supported at the back upon ledges 20, and along their slit edges by means of a plurality of guides 22, 23 and 24, that are carried by the fixed

sidewall 19. The guides have vertical legs 25, 26 and 27, respectively, and horizontal legs 28, 29 and 30, respectively. The vertical legs of the guide have mounting flanges 31, 32 and 33, which seat within a recess 34 in the fixed side wall 18 of the magazine. Wall 18 has a longitudinally extending slot 35, and bolts 36, 37 and 38 extend through the mounting flanges of the guides and the slot to adjustably position the guides relative to the magazine. Although the guides have been described as having vertical legs, these legs actually incline slightly to the rear in order to hold the partition strips at a slight angle. The recess 34 and the slot 35 in wall 18 are positioned at right angles to the upwardly extending legs of the guides. This particular arrangement is best shown in FIG. 12 of the drawings.

The guides are so adjusted relative to the wall 18, that their vertical legs are spaced apart a distance equal to the spacing between notches in the strips which the magazine is to hold. Leg 25 of the strip 22 is positioned a similar distance from the backplate 19 of the magazine. Due to this arrangement, the vertical legs of the several guides will enter the notches in the partition strips and hold the strips against movement in any direction except vertically. It is to be noted that the guide legs project transversely from the wall 18 so as to extend a substantial distance within the strip notches.

The horizontal legs 28, 29, and 30 of the guides 22, 23 and 24 are spaced vertically from one another, as seen in FIG. 12. The horizontal legs extend beyond the magazine 9, and end in horizontally staggered relation, with the leg 28 being the bottom leg and terminating closest to the end of the magazine. The end of the horizontal legs are staggered to an extent approximately equal to the spacing between the vertical legs of the guides. The horizontal legs provide tracks to guide the flaps formed between the slits along the edges of the partition strips.

The vertical sections of the guides are joined to the horizontal sections of the guides by arcuate sections 39, 40 and 41. The arcuate sections are rather small curves, and they, in effect, form seats for the edges of the notches of the strips as each strip becomes the bottom strip of the supply pile. It will be clear, then, that the bottom strip of the pile is supported at the back upon the ledges at the bottom of the backplate 19, and along the slit edge upon the arcuate sections of the strip guides. This defines the angular position of the strips of the supply in the magazine.

As the strips are ejected from the magazine, they will be moved to the right, as viewed in FIG. 12, to the position shown by the gathered group of five strips at the center of that FIG. of the drawings. As the strip is moved forward, the trailing edge of each notch will cam about the bottom of the arcuate section of the guide with which it is in engagement. The leading edge of each notch will be supported upon the top of the underlying horizontal section of the guide upon which it rests. Thus, each of the four tabs, or flaps, formed along the edge of each strip will be turned and separated vertically from its adjacent tabs, so that each tab lies in a separate horizontal plane. The end tab, that is the tab at the leading end of the strip, will lie fully above the horizontal leg 30 of the guide 24. The next succeeding tab will lie between the horizontal legs 29 and 30 of the guides 24 and 23. The next tab, in order of progression, will lie between the horizontal legs 29 and 28 of the guides 23 and 22, and the trailing tab will lie wholly beneath the horizontal leg 28. This positions the tabs in substantially horizontal planes, with the planes spaced vertically. By reason of this, the strips will be held at an angle, and the spaces between successive tabs will be spaced vertically. This means that the edge of each slit is spread apart vertically to provide a throat into which the strips of the other group may enter when the strips of the two groups are brought together for assembly. This position of the tabs and the separated sides of the notches in the strips 3 of the gathered group is clearly shown in FIG. 5-A.

The means for ejecting, gathering and advancing strips 3 to the assembly position is illustrated in FIGS. 2, 4-B, 8 and 11. The strips in the magazine 9 are contacted successively by

pickup lugs 42 carried by a gathering bar 43. The bar is mounted upon a carriage 44 that travels along tracks 45 mounted on the underside of the movable rail 15 of the table. By reason of this mounting, the gathering bar will maintain its position relative to the movable wall 16 of the magazine 9, irrespective of the position of adjustment of the wall. The wall, rail, tracks and carriage move as a unit.

Carriage 44 is in the form of a plate 46, upon which a plurality of track following rollers 47 is mounted. The track is composed of cylindrical rails, and the rollers have arcuate surfaces to embrace the opposite sides of the rails, so as to fully support the carriage in depending relation from the track. Gathering bar 43 is attached to plate 46 by means of a plurality of arms 48, and the gathering bar and carriage 44 are caused to move back and forth along the track by means of a crank 49 mounted upon a drive shaft 50 journaled in bearings 51 on the end plate 13 at the magazine end of the machine. The drive shaft extends horizontally across the machine, and is rotated by a motor 52 through a reduction gearing 53. The crank is connected to one end of a pitman rod 54 which has its opposite end connected to an extension 55 on the plate 46 of the carriage 44. The plate extension projects through a slot 56 in the movable rail 15 of the table. Rotation of the crank 49 draws the carriage in one direction, to pick up a gathered group of strips 3 and move them to their assembly position, and then returns the carriage to its starting position.

Gathering bar 43 is inverted T-shape in cross section, (See FIGS. 13, 14, and 18) and the pickup lugs 42 are of inverted U-shape to straddle the vertical leg of the T. Any suitable means 57 is used to fix the lugs in spaced relation along the gathering bar. Each lug has a lip 58 at its leading end which projects forwardly above the top edge of the gathering bar, and forms a seat 59 to embrace the trailing end of the bottom strip in magazine 9, and, when the strip is seated, move it forwardly from beneath the pile. Thus, the partition strips are picked up in sequence, and moved forward with the trailing edges supported in the seats 59 and the slit side edges guided by the horizontal legs of the guide strips. This will not only support the individual strips during movement to the assembly position, but will also maintain the proper strip angle and parallel relation to one another.

In order to facilitate removal of the bottom partition strip from the pile in the magazine 9, means are provided to lift the pile from the bottom strip during the ejection movement, so that the bottom strip can move freely out of the magazine. This mechanism is shown most clearly in FIGS. 1-B, 2, 3 and 13 through 18. The mechanism includes a pronglike member, which impales the bottom strip to hold it in downward position, and a second pronglike member, which engages the next upper strip and lifts this strip and the superimposed pile.

Referring more particularly to FIGS. 15 through 18, the pile-lifting mechanism includes a plate 60 that is pivotally mounted on a shaft 61 carried by a mounting bracket 62 fixed to the movable sidewall 16 of the magazine 9. The plate has a rearwardly disposed offset 63 at its bottom, with downwardly extending, spaced legs 64 that define an opening through which a pile-lifting prong 65 moves, and in which it is supported. The prong is a wedge-shaped member, having depending ears 66 connected by pivots 67 to the legs 64. The prong has a strip-engaging, serrated edge 68 at its front, and an upstanding lip 69 at its top. The lip is held in yielding engagement with a ledge 70 at the rear edge of the plate offset 63, by means of a spring 71 secured to the plate 60, at 72, and having a finger 73 in contact with the back of the prong. Spring 71 urges the prong in a rearward direction about the pivots 67. An arm 74 is also pivotally mounted on shaft 61. This arm carries a second, pointed prong 75 at its bottom, to engage, and hold, the bottom strip of the pile in the magazine against lifting when the remainder of the pile is lifted. Arm 74 is held in spaced relation to plate 60 by means of an abutment screw 76 that is threaded through the arm and held in yielding abutment with plate 60 by means of a spring 77, fixed at one end to plate 60, at 78, and having its other end overlying the arm 74.

The assembly of plate 60 and arm 74 is normally held in inoperative position by means of a coil spring 79 that is connected at one end to plate 60 and has its other end fixed to a mounting bracket 80 on the rail 15. The movement of arm 74 toward magazine 9 is limited by means of an abutment screw 81, which is threaded through the arm and passes freely through an opening 82 in plate 60 for contact with wall 16 of magazine 9. This allows the prong 75 to be brought into light contact with the bottom strip in the magazine, yet permits the plate 60 to continue to move to cause the prong 65 to engage, and lift, the pile above the bottom strip.

The assembly is moved inwardly, and the prongs moved through an opening 83 in plate 16 into contact with the partition strips, by means of cams 84 on the strip-gathering bar 43, under the control of a toggle linkage 85 that shifts the assembly into the path of movement of the cams 84, or allows it to move away from the cams under the influence of coil spring 79. The control linkage, in turn, is actuated by a shift rod 86, moved by reciprocation of the gathering carriage 44.

Shift rod 86 is mounted in guides 87 fixed to rail 15. At each end, the rod carries a strike block, the block at the magazine end of the machine being shown at 88, and the block near the discharge end being shown at 89. These blocks are struck, and the rod shifted, by a lug 90 carried by the extension 55 of the plate 46 of carriage 44. Movement of the carriage to the full extent of its gathering and ejecting stroke will cause lug 90 to strike block 89 and shift rod 86 to the right, as viewed on the drawings, to move the pile-lifting assembly out of the path of cam 84 during the return stroke of the carriage, so that the assembly will be inactive during that portion of the carriage stroke. At the end of the return stroke, the lug will strike block 88 and shift rod 86 to the left to position the lifting assembly for operation during the gathering portion of the stroke of the carriage.

Toggle linkage 85 is actuated by a control member 91, fixed to shift rod 86. This member is connected to one end of a link 92, that has its opposite end pivotally connected to one arm of a bellcrank toggle link 93. The other arm of link 93 is pivotally attached to the bracket 80 on rail 15. Intermediate its ends, link 93 has a pivotal connection to one end of a second toggle link 94, which is pivotally attached at its other end to a block 95 slidably mounted on a rod 96 supported on bracket 80. Block 95 carries a bumper 97 for contact with plate 60 of the strip lifting assembly to move the assembly toward operative position, so that it may be actuated by cams 84 as the gathering bar 43 moves through magazine 9.

FIGS. 13 and 14 show particularly the operation of the toggle linkage, while FIG. 15 shows in dotted lines the position of bumper 97 relative to plate 60. FIG. 14 illustrates the toggle linkage in broken, inoperative position, caused by lug 90 striking block 89 and shifting rod 86 to the right at the end of the carriage-ejecting stroke. This moves control member 91 to the right, pulling link 92 with it, to swing the toggle links out of alignment and draw block 95 with bumper 97 rearwardly away from plate 60, allowing the lift assembly under pull of spring 79 to swing back to inoperative position, out of the path of movement of cams 84. This position of the toggle linkage and lift assembly is shown in FIG. 14, and the position of the lift assembly is shown in dotted lines in FIG. 16. Thus, the carriage is free to return to its starting position without actuation of the pile-lifting mechanism. As the carriage reaches the end of its return stroke, the lug 90 will strike block 88, shifting rod 86 to the left. This moves control member 91 to the left also, exerting a pushing force on link 92 to swing the toggle links about their pivots and bring them into alignment. This moves block 95 inwardly, causing bumper 97 to strike plate 60 and move the pile-lifting assembly into position for operation. At this time, the pile-lifting mechanism will be in the position shown in full lines in FIG. 16.

Cams 84 are adapted to contact a cam follower roller 98, mounted on plate 60 and depending below the remainder of the lifting mechanism into the path of cams 84. Cams 84 have vertical cam elements 99, connected to lugs 42 of gathering

bar 43 by means of horizontal extensions 100 (See FIGS. 13, 14 and 18). Each cam element has a leading, inclined surface 101, a flat surface 102 parallel to the direction of travel, and a trailing, declining surface 103. As the cams move in the direction of the arrow in FIG. 13, the inclined surface 101 of the leading cam will strike the cam follower roller 98 and move the lifting assembly inwardly as the roller moves up the inclined surface. As this occurs, plate 60 and arm 74 are swung inwardly about the shaft 61 to bring the prongs 65 and 75 into engagement with the bottom strip of the pile and the next adjacent strip. At about the time that prong 75 contacts the bottom strip of the pile, abutment screw 81 will strike the magazine sidewall 69 and prevent further inward movement of the arm 74. Spring 77 will hold the arm in this position, and prong 75 will exert sufficient pressure to maintain the bottom strip in its original position. Prong 65 will have contacted the next adjacent strip, and continued inward movement of plate 60 will cause prong 65 to impale the end of the strip. As the prong edges seat within the strip end, the prong will move no further inwardly, but continued movement of the plate 60 will cause the prong to rock rearwardly about the pivotal connection of the ears 66 to the offset portion of the plate. The prong, therefore, will tilt upwardly, lifting the strip to which it is impaled, and the pile of strips above. This position is shown in FIG. 18 of the drawings. With the parts in this position, continued forward movement of the gathering bar 43 will move the flat surface 102 of the cam into contact with the cam roller 98. As the roller follows the flat surface, the leading pickup lug 42 on the gathering bar will move forwardly so that the bottom strip of the pile will become engaged in the seat A machine and be partition forwardly out of the magazine. During this movement, the various flaps on the edge of the strip will become separated by move the bottom of the flap edges around the arcuate sections 39, member and 41 and onto the horizontal legs 28, 29 and 30 of the strip guides 22, 23 and 24, as previously described. As the bottom strip begins to move from the magazine, the cam follower will move down the declining trailing portion of the cam, and the lifting assembly will move back to its original position. This operation will be repeated as each of the five lugs move into position at the magazine to pick up strips. Each time the pile will be lifted from the bottom strip to relieve the bottom strip of the frictional weight of the remainder of the pile. It is only necessary for each strip to move a short distance to be removed of the weight of the pile, due to the inclined position of the strips within the pile. When the five strips have been gathered and moved to the point of assembly, lug 90 will strike block 89 and shift rod 86 to break the toggle linkage and allow the pile-lifting assembly to move back to inoperative position, out of the path of movement of cams 84, so that there will be no movement of the lifting assembly during the return stroke of the carriage.

Referring now particularly to FIGS. 1-B, 3, 10 and 12, as the several strips 3 gathered on the bar 43 move from the magazine, they move off of the horizontal legs 28, 29 and 30 of the strip guides 22, 23 and 24, into additional guides formed at the edges of a plurality of bedplates 104, 105, 106 and 107, which, in part, make up the table 8. These plates are held in vertically spaced, parallel relation by means of separators, or spacers, 108. The plates are spaced apart a distance greater than the thickness of the strips, so that the long strips 2 of the inner pack assembly, supplied from the magazine 10, can slide freely between them for assembly with the strips 3, as will be described.

The edges of the bedplates adjacent the path of movement of the gathered strips 3, as mentioned above, have guides to maintain the separated condition of the various tabs of the strips. The top plate 104 has a guide ledge 109 along its lower edge. (See FIG. 10) The leading flap of each of the gathered strips 3 will ride upon the upper surface of this ledge, so that the leading flaps will be held against downward movement. The next to top bedplate 105 has an upper guide flange 110 and a lower guide ledge 111, with the two being separated ver-

tically to form a guide channel 112 between them. The next to leading flaps of the strips 3 will ride in this channel so that they will be held against vertical movement in either direction, and separated by a considerable extent from the leading flaps of the strips. This will hold the edges of the first slit, or notch, 5 of each strip spread apart, and straddling the space between the upper and next adjacent bedplate to permit easy entry of a strip 2 moving through this space into the tapered throat of the notch for assembly with strips 3. The next to bottom bedplate 106 also has an upper guide flange 113 and a lower guide ledge 114, forming between them a channel 115. The next to trailing flaps of the strips 3 will ride in channel 115, so that the middle notch of the strip will have its edges separated and bridge the space between the second and third bedplates 105 and 106 to permit free movement of a second longitudinal strip 2 through the space between these two plates into the centermost notches of the gathered strips 3. The bottom plate 107 has an upper guide flange 116, but needs no lower ledge. The trailing flap of each of the gathered strips 3 will ride beneath the guide flange 116 to hold the last of the notches in spread position across the space between the two lower bedplates through which a third longitudinal strip 2 is moved into position. The gathering bar 143 will move the gathered partition strips 3 along their several guides to an assembly position indicated at 117 in FIG. 1-B.

Turning now to the magazine 10 for the longitudinal partition strips 2 and its ejecting mechanism, FIGS. 1-B, 4-B, 7 and 11 are most important.

The magazine 10 is mounted upon a platform 118 supported in part upon the sideplate 12 of the machine frame and in part upon a bracket 119 fixed to the side of the sideplate 12. The magazine consists of a front mounting rail 120 having vertical guides 121, a side rail 122, fixed to the platform 118 and having vertical guides 123, a side rail 124 which is movable relative to the side rail 122 and carries vertical guides 125, and a back rail 126 that is movable relative to the front rail and carries vertical guides 127. Back rail 126 is adjustably secured to the platform 118 by means of bolts 128 which pass through slots 129 in the platform 118. This permits movement of the back rail toward and from the front rail to adjust for various depths of partition strips 2. The front rail is fixed to the platform at one end, and to the fixed side rail 122 at the other end. The bottom of rail 120 is spaced from the platform to form a slot 130 of sufficient depth to permit partition strips 2 to be ejected from the magazine, as will be described. Side rail 124 is connected to the front rail by means of bolts 131 which pass through slots 132 in the rail 120 to allow adjustable positioning of the side rail 124 relative to the side rail 122 for lengthwise adjustment of the magazine.

The back rail 126 of the magazine 10 also has a slot 133 to permit entry of an ejector plate 134 to push the bottom strip 2 of a supply in the magazine from the magazine through the slot 130 at the bottom of the front rail. The ejector plate is connected at its back edge to a carriage 135 that carries rollers 136 movable along parallel, transversely positioned, tracks 137 mounted on the bracket 119. Movement of the carriage along the tracks 137 causes the ejector plate 134 to move into and through the magazine and return. Each time the ejector plate moves through the magazine, one partition strip is ejected.

Carriage 135 and ejector plate 134 are caused to move by means best illustrated in FIGS. 4-A, 4-B, 11 and 21. The mechanism includes a bellcrank 138, pivotally mounted upon a bracket 139 fixed to one of the depending sides of the platform 118. One arm of the bellcrank is connected to an extension 140 of the carriage 135, and the other arm of the bellcrank is pivoted to one end of a rod 141. The other end of rod 141 is connected to a lever 142, which is pivotally mounted on ears 143 projecting outwardly from the frame end plate 13. Lever 142 carries a cam-following roller 144, which moves within a cam track 145 formed in a cam 146 mounted on the drive shaft 50. The cam track 145 has three high areas 147, designed to hold the ejector plate 134 in its position of rest,

and three low areas 148, designed to hold the ejector plate in fully ejected position. The areas joining these highs and lows cause the reciprocating movement of the ejector plate. The cam also has a bypass track 149 connecting two of the high areas, so that those two high areas in effect become one, to cause the ejector plate to make but two ejecting movements per cam revolution. In order to cause a change of operation in the ejector movement, a control lever 150 is pivotally mounted on the end plate 13, and has one position in which it extends toward the magazines and another position projecting beyond the discharge end of the machine. In FIG. 21, the control lever is shown in its position extending beyond the discharge end and set to eject three partition strips during each revolution of the cam. A coil spring 151 is connected between lever 150 and the cam following lever 142. In the position shown in FIG. 21, the spring is acting to urge to the cam-following roller 144 toward the inner wall of the cam track 145. This will cause the roller to follow the inner wall of the track, thus providing for three ejection movements per revolution of the cam. If the lever is turned in the opposite direction, spring 151 will urge lever 142 in a reverse direction to cause the roller 144 to bear against the outside wall of the cam track 145. Under these circumstances, the roller will move along the bypass track 149, so that only two ejection movements will be made per cam revolution.

It is necessary that the partition strips 2 ejected from the magazine 10 be collected in vertically spaced relation and maintained in that condition until assembly with the partitions 3 which are gathered at the assembly point 117. An elevator 152, having vertically spaced shelves, is used for this purpose. This structure can be best seen in FIG. 1-B, 9 and 11.

The elevator 152 is composed of a plurality of horizontal plates 153, which are held in vertically spaced, parallel relation by means of spacers 154 at their back edges, and spacers 155 intermediate the front and back edges. The plates have transverse slots 156, and bolts 157 pass through the slots and the spacers 155 to permit the spacers to be adjustably positioned relative to the edge of the elevator adjacent the magazine 10. This allows the transverse depth of the receiving shelves for the partitions 2 to be adjusted to receive partition strips of various depth.

The elevator is mounted upon a carriage 158 which includes a frame 159 upon which rollers 160 are mounted. The rollers ride upon vertical tracks 161 mounted on brackets 162 fixed to the side plate 11 of the machine frame.

The carriage is moved by means of a bellcrank 163, also mounted on the sideplate 11. A link 164 joins one arm of the bellcrank to the frame 159 of the elevator carriage. The other arm of the bellcrank is connected to a rod 165 that has its opposite end attached to a control lever 166 pivotally mounted on ears 167 on the end frame 13. Lever 166 carries a cam following roller 168, which moves in a cam track 169 in a cam 170 fixed to the drive shaft 50. Cam track 169 has three stepped rises, 171, 172 and 173, and an inoperative level 174. When in inoperative position, the top shelf, that is the space between the two upper plates, is below the level of the outlet slot 130 at the bottom of the plate 120. During its cycle of movement, the elevator moves one step to bring the upper shelf into the plane of the outlet slot 130, and the ejector operates to push the bottom strip from the pile in the magazine 10 onto this shelf. As the ejector moves back, the elevator moves one step upward to bring the next shelf to the plane of the strip feed and the ejector moves again. As the ejector retracts, the elevator comes up to its final level. It receives a third strip from the magazine, and the elevator then moves down to bring the shelves into alignment with the spaced between the bed plates 104, 105, 106 and 107 of the table 8, to position the gathered strips 2 for movement from the elevator into the spaces between the table bedplates.

The means for moving the gathered strips 2 from the elevator into the bedplate spaces is shown most clearly in FIGS. 1-B, 4-A, 4-B, 7, 11, 19 and 20.

The transfer mechanism includes another carriage 175, having a frame 176 carrying rollers 177 which ride on horizontal tracks 178 supported on the frame side plate 12. The carriage supports a transfer bar 179 which actually engages, and moves, the gathered partition strips 2 from the elevator.

Carriage 175 is given a reciprocatory movement along the tracks by means of a cable 180, connected to the carriage and passing around a first pulley 181, fixed to the frame side plate 12 near the forward end of the elevator, and a second pulley 182, also mounted on the plate 12, but adjacent the magazine end of the machine. Pulley 182 carries a small spur gear 183 in mesh with a gear sector 814, forming one arm of a bellcrank 185 mounted upon ears 186 fixed to the end frame 13. The other arm of the bellcrank carries a roller 187 which follows a cam path 188 on a cam 189 mounted on the drive shaft 50. The cam path of cam 189 is so designed that carriage 175 will move forward to transfer the strips 2 from the elevator into the bedplate spaces and return rather quickly, while remaining idle during most of the remaining cycle of the machine.

Transfer bar 179 is composed of three sections, a base member 190, an intermediate member 191, and a top member 192. The bottom member 190 is the smallest of the three, while the intermediate member 191 is considerably larger and the top member 192 is larger still. The members each carry a forwardly extending, bifurcated member which define seats 193, 194 and 195, to embrace the trailing edges of the three partition strips gathered in the elevator. In view of the fact that the transfer bar travels between the wall of the frame sideplate 12 and the adjacent edge of the elevator, the side edges of the partition strips will be received within the transfer bar seats. In order to have a more extended pressure against the trailing end of the partition strips, pusher fingers 196, 197 and 198 extend transversely out from the respective transfer bar members, with their leading edges forming a continuation of the seats within the members. Whereas the transfer members with their seats travel in the space between the frame and the elevator, the pusher fingers move within the spaces between the elevator plates. The three members are assembled for adjustment by means of bolts 199 which extend through slot 200 in member 191 and slot 201 in member 192. The bolts are threaded into the bottom member 190. By loosening the bolts, the members may be adjusted to place the fingers at predetermined points in advance of one another, so that the transfer movement of the bar will position the several strips 2 in progressively stepped relation.

When the gathered strips 2 are transferred to the table, they come to rest against stops 202 located between the several bedplates of the table 8. These stops are arranged in the same stepped relation as are the pushing surfaces of the several members of the transfer bar, to locate the partition strips 2 properly for insertion into the gathered strips 3. In order to be certain that the partition strips will be properly positioned, each of the seats in the members of the transfer bar have swinging dogs 203, the dogs being pivotally connected to the members by means of pivot pins 204 located in recesses 205 in the jaw above the seat in which the dog is mounted. A spring 206 normally urges the dogs into strip-engaging position.

After both sets of partition strips have been gathered and properly positioned at their respective stations for insertion, inserting means move the prepositioned strips 2 transversely of the machine to engage the slits of the strips 2 with the spread slits of the angularly positioned strips 3. The mechanism for accomplishing this is best seen in FIGS. 1-B, 3, 4-B 7 and 10.

Here, again, the movement of the strips is accomplished by reciprocating a carriage 207 along tracks 208. The carriage frame 209 has rollers 210 mounted on it, and the rollers ride upon the cylindrical rails which from the track. The actual inserting is done by three vertically spaced, inserting plates 211, 212 and 213, attached to the carriage. When the carriage is at its rest position, the inserting plates have their leading edges within the spaces between the several bedplates making up the table 8. Each of the several plates is slotted, as at 214, and ap-

propriate means is used for securing the plates in selected, adjusted positions relative to the carriage. This permits the plates to be progressively staggered as are the partition strips, and also to be more widely separated if necessary to accommodate strips of different length.

Carriage 207 is moved by means of a bellcrank 215, pivotally mounted on a bracket 216 secured to the sideplate 12 of the machine frame. One end of the bellcrank is connected by means of a link 217 to the carriage frame. The other arm of the bellcrank is connected by a rod 218 to a lever 219 pivotally attached to ears 220 on the end plate 13. The lever carries a cam-following rollers 221, which rides upon a cam surface 222 of a cam 223 mounted on the drive shaft 50. The cam surface 222 is so designed that the inserting plates make one inserting movement and return to their positions of rest each revolution of the drive shaft.

As the inserting plates move across the machine between the bedplates of the table 8, they push the staggered and spaced partition strips ahead of them. These strips are positioned so that their slits, or notches, move into the open throats of the spread notches of the gathered group of strips 3. Continued movement of the inserters cause the notches of the strips 2 to straddle the solid portions of the strips 3 beyond the notch ends to complete the assembly. By reason of the inclined, spaced, progressively staggered relationship of the strips 3, and the spaced, staggered relationship of the strips 2, the strips are brought into absolute registration and complete assembly with the single insertion movement. When the inserting plates complete their forward motion, the assembly of the inner pack is completed.

The gathering bar 43 has an extension 224 (See FIG. 1-B and 8) which projects from the gathering bar and carries a spring-ejecting finger 225 to engage the assembled inner pack, 35 when the gathering bar is withdrawn to its position of rest, and to push the completed inner pack from the machine as the gathering bar begins a gathering movement. Due to the spring characteristics of the ejecting finger 225, the finger can flex to move under the assembled unit at the assembly position 117 40 on the return movement of the gathering bar. As soon as the ejecting finger passes the end of the assembled inner pack, it springs upward into position to engage the pack and discharge it as the gathering bar moves forward. The discharge movement of the extension pushes the assembled pack onto a receiving table 226 at the discharge end of the machine. The table is mounted upon brackets 227 carried by the end plate 14. An operator can remove the completed packs from the table.

It was mentioned above that the rail 15, on which the magazine 9 and its operating mechanism are mounted, was adjustable to provide for reception of strips of different depth in the magazine 9. This is accomplished by providing an end plate 228 at the magazine end of the machine, which plate is fixed to the rail 15. The end plate has slots 229, and bolts 230 secured the end plate in positions of adjustment to the end cross member 13. At the opposite end of the rail, there is a slot 231 in the rail and a bolt 232 adjustably fixes the rail to the frame end plate 14. The end plate 228 carries a lug 233, and an adjusting screw 234 is rotatably mounted in the lug. The screw is threaded through the frame sideplate 11 and rotation of the screw will move the end plate 228 and rail 15 toward and from the frame sideplate 11 when the bolts 230 and 232 are loosened. When the rail is in an adjusted position, the bolts 230 and 232 can be tightened and the rail will be held rigidly in place.

As the operation of each of the several mechanisms of the machine has been given in connection with the description of the particular mechanism, and the mechanisms have been described in the sequence of their operation, it is believed that the overall operation of the machine will be clear without a review of the operation.

Turning now to that form of the machine illustrated in FIGS. 22 through 33, the machine is essentially the same as the one just described, but the short strip feed magazine (cor-

responding to the magazine 9 of the first described form) and its stripfeeding mechanism is slightly modified. The means for discharging assembled packs from the machine is also different in this embodiment of the machine.

The frame of the magazine has the sideplates 235 and 236 connected at the discharge end of the machine by an end plate 237. There will also be an end plate at the magazine end of the machine, but this part of the frame has not been shown. The frame supports a table 238, which includes a movable, and adjustable, side rail 239, as in the previous form.

Movable side rail 239 supports a sidewall 240 of a strip magazine 241, so that wall 240 will move with adjusting movement of rail 239. The fixed wall 242 of the magazine is supported on the frame sideplate 235, and carries strip guides 243, 244, and 245, similar to the strip guides of the first form. The mounting flanges of the several guides are adjustably attached to the backwall 242 of the magazine by bolts which pass through an adjusting slot in the wall 242. The guides differ from those previously described in having ledges 247 on which the flaps along the slit edges of the bottom strip in the magazine will rest. The guides also have guide faces 248 which engage the slit edges of the strips in the magazine to prevent edgewise movement of the strips. The ledges 247 are spaced below the bottoms of the guides faces 248 a distance just slightly greater than the thickness of the strips in the magazine to allow the bottom strip to move transversely as will be later described. In this embodiment, the movable wall 240 has an inwardly extending lip 249 to support the unslit edge of the bottom strip in the magazine. There is no need for front or back guide members in the magazine, as the strips are held in proper stacked relation within the magazine by means of the engagement of the slits of the strip with the strip guides 243, 244, and 245.

The ledges 47 of the guides 243, 244 and 245 lie at an angle to the horizontal to position strips at the proper angle for movement along the horizontal portions of the guides and to the assembly position. As the strips are moved from the magazine to the assembly position, adjacent edges of adjacent flaps of the strip are caused to be spread apart as described in detail in connection with the first form of the invention. As this action is exactly the same as it was in the previous form, and is performed by exactly the same means, that is the horizontal portions of the guide strips, a redescription of that action is not necessary.

As the strips of the pile in the magazine move downwardly as bottom strips are ejected, they are held against the movement transversely of the machine by engagement with the movable sidewall 240 of the magazine and with the guide faces 248 of the guide strips. They are held vertically by engagement of the bottom strip with the lip 249 on the movable wall 240 and the ledges 247 of the guide strips. The lip 249 will be at the same angle as the angle of the ledges 247 in order to properly support the bottom strip along its full length. Therefore, it is necessary to disengage the bottom strip from the lip in order for the strip to move downwardly around the curved portions of the guides and then in a truly horizontal direction to the assembly point. Of course, even through the strip as a whole moves horizontally, the strip maintains its inclined position.

The first form of the invention included mechanism to render the stack-lifting means inoperative during the retraction stroke of the gathering bar and to make it operative during the gathering stroke. In the modified form there is means to activate and deactivate mechanism for moving the magazine bottom strip transversely to move its edge off of the lip 249. This mechanism is best shown in FIGS. 22, 23, 28 and 30 through 33.

The means for moving the bottom strip transversely includes a pusher blade 250, which is an elongated member movable through a slot 251 in the magazine wall 240. The blade is mounted upon a block 252 that slides transversely of the rail 239 on rods 253 fixed to the movable sidewall 240 of the magazine.

Movement of the block along the rods will cause the blade to move through the slot 251 into contact with the unslit edge of the bottom strip of the pile and push the strip toward the fixed backwall 242 of the magazine. The strips above the bottom one are held against similar movement under the frictional pull of the bottom strip by their contact with the guide faces 247 of the strip guides.

Block 252 is caused to move on the rods by means of a lever 255, pivotally mounted intermediate its ends in a bracket 256 carried by the rail 239. One end of the lever is pivotally connected to block 252 by means of a pin and slot connection 257, which is necessary due to the straight line movement of the block and the arcuate movement of the lever arm. The arm of the lever 255 which is connected to the block is biased toward inoperative position of the block and pusher blade by means of a spring 258 attached to the lever arm and to the rail 239. The opposite end of lever 255 is pivotally connected to one end of a cam follower 259, that carries a roller 260 for operative contact with the cam 261 carried by a strip-gathering bar 262, similar to the one in the first described form. The opposite end of the cam follower is pivotally connected to one end of an actuating link 263, that has its opposite end connected to one arm 264 of a bellcrank 265 which is pivotally mounted at its center on the bracket 256. The other arm, 266, is connected to a link 267 that has its opposite end connected to a control block 268 fixed to a shift rod 269. The shift rod is mounted in bearings 270 on the side rail 239, and carries strike blocks 271 and 272 at its ends, which are struck, and caused to move, by a lug 273 fixed to a carriage 274 that mounts the gathering bar 262.

Referring particularly to FIGS. 30, 31 and 32, it will be seen that when the gathering bar 262 travels to the limit of its retracting movement, that is to the left, lug 273 will strike block 271 causing rod 269 to move to the left. This moves the control block 268 to the left, forcing the bellcrank 265 to rotate in a clockwise direction and exert a pulling force on cam follower 259 to swing the cam follower about its pivotal connection with the lever 255 and move it inwardly to place the roller 260 in the path of movement of the gathering bar cams 261. As the gathering bar moves in an operative, or strip-gathering direction, that is to the right, each cam 261 will contact roller 260 and move the roller outwardly. This will cause lever 255 to swing about its pivot on the bracket 256 and move block 252 and the pusher blade inwardly. As the blade moves through slot 251, it contacts the uncut edge of the bottom partition strip of the pile in the magazine and pushes it toward the backwall. In view of the fact that the strip guide ledges 247 are spaced below the bottoms of the guide faces 248, the flaps along the slit edge of the strip can move freely toward the backwall beneath the bottoms of the guide faces. When the uncut edges of the strip moves off of the supporting lip 249, and the pusher blade 250 moves back under the influence of spring 258, the weight of the strips in the magazine will be imposed upon the unsupported edge of the bottom strip to force that strip downwardly. Due to the fact that there is some flexibility in the strip, and the strip is no longer supported along its uncut edge, it will be free to drop down into the path of the pick up lugs 275 carried by the gathering bar 262. This position of the bottom strip is shown in dotted lines in FIG. 33.

This movement will be repeated as each cam 261 of the gathering bar contacts and moves the cam follower 259. Thus, in the embodiment shown, five strips will have been moved toward the rear of the magazine and been picked up by the gathering bar lugs and moved in properly oriented condition to the assembly point. When the gathering bar completes its movement, the lug 273 on the gathering bar carriage will strike block 272 and shift rod 269 to the right. This will cause the bellcrank 265 to be rotated in a counterclockwise direction and, through link 263, exert a pushing force upon cam follower 259 to rotate the cam follower about its pivotal connection with lever 255 to a position out of the path of movement of the gathering bar cams 261. This position is

shown in FIG. 32. With the mechanism in this position, the gathering bar can return to its starting position without causing any of the strips within the magazine to be moved toward the backwall.

As in the previously described form, carriage 274 is mounted upon tracks 276 beneath the movable side rail 239. The carriage is caused to move along its reciprocating path by means of a pitman 277, connected to the carriage, and to a crank 278, mounted on the drive shaft 279. As the remaining structure of the gathering bar assembly is identical to the arrangement described in detail in the first form, it will not be further described.

When the gathering bar moves the gathered strips 3 to the assembly point, the several flaps of the strips travel along the horizontal legs of the strip guides, as previously described, and into guides formed along the edges of vertically spaced bedplates 280 of the table 238. These guides are identical to the ones in the previously described form. Thus, the strips are positioned in vertically spaced relation and inclined, with their slit edges being spread in exactly the same manner as before, ready to receive the strips of the other group to form the assembled package.

A supply of strips for the other group are maintained in a magazine 283, constructed exactly as the magazine 10 of the first described form and been not be described again. Strips are moved from the magazine by an ejector plate 284 mounted on a carriage 285 supported on rails 286 on a bracket 287 on the back side of the machine. The carriage is moved by means of a bellcrank 288, a rod 289, and a cam (not shown) on the drive shaft 279. Here, again, the mechanism is identical to that previously described.

The strips ejected from magazine 283 are inserted into the shelves of an elevator 290. The elevator is mounted upon a carriage 291, and is caused to rise step by step as the ejector plate is operated to position the shelves to receive strips. The movement is accomplished in the same manner as in the original form. When the elevator has strips in all of its shelves, it moves downwardly to place the strips in alignment with the spaces between the bed plates 280 of the table, so that they can be moved into position for assembly. The gathered strips are moved from the elevator to the inserting position by means of a transfer bar 292, mounted on a carriage 293 which is operated as in the first form. The strips are moved into position between the bedplates of the table opposite the gathered short strips at the assembly point.

The assembled long strips are then pushed transversely of the table and into assembled relation with the short strips by means of a series of inserting plates 294 mounted upon a carriage 295, also operated by the same control mechanism as in the first form. The long strips are moved between the plates and into the spread throats of the slits of the group of short strips, and brought into assembled position as previously described.

In this form of the invention, the inserting mechanism has an added function. It not only moves the gathered group of long strips into assembled relation with the gathered group of short strips, but it serves also to discharge the assembled pack from the machine. The means by which this is accomplished is shown best in FIGS. 22, 23, 24 and 29.

It will be noted that when the gathered short strips 3 are moved to the assembly position their flaps ride in the grooves, or upon the ledges, formed along the adjacent edges of the table bedplates 280. As the strips enter the assembly position, their uncut edges engage a retaining plate 296. The plate stands vertically, and is opposite the support ledges of the table bedplates. Its position relative to the bedplates is such that the strips 3, through contact with the plate, are pressed tightly against the bedplates. The end of the retaining plate adjacent the magazine 241 has a tapered portion 297 to lead the strips into the assembly position, and cam their flaps into engagement with the edges of the table bedplates. Thus, the assembled strips are held at the assembly position by engagement of the spread flaps with the several control ledge sur-

faces on the bedplates, and by the frictional contact of the retaining plate 296 against the opposite edges of the strips.

Plate 296 is mounted adjacent its ends on arms 298, and these arms are pivotally connected at their tops, at 299, to mounting pedestals 300 fixed to the movable side rail 239. This provides a mounting which will enable plates 296 to swing toward and from the strips at the assembly position. The positioning of the strip is accomplished by mechanism under the control the inserting plate assembly.

The control means includes a shaft 301, journaled in bearings 302 supported on the movable rail 239. The shaft carries a bellcrank 303, operated by the inserter plate assembly and controlling the positions of arms 298 and retaining plate 296. The bellcrank has a central operating arm 304, keyed to shaft 301, and a pair of arms 305 fixed to the ends of shaft 301 and coupled to the arms 298. The coupling between the bellcrank arms and the retaining plate-mounting arms is by means of pins 306 carried by the bellcrank arms 305, which pins are movable within slots 307 in plates 308 attached at the bottoms of the arms 298. The slots have lower, vertical, locking portion 309, and, when the pins 306 are in the locking portion 309, the arms 305 of the bellcrank are substantially horizontal so that there is a straight thrust from the shaft 301 through arms 305 to the arms 298 and the retaining plate 296 to lock the plate in strip-engaging position, as shown in full lines in FIG. 29. Slots 307 incline inwardly as they rise from the locking portions 309. The inclined portions of the slots 310 slope toward the plate 296 as they rise upwardly, and the slots terminate at their top in an upper, vertical, locking portion 311.

Referring particularly to FIG. 29, it will be seen that when the bellcrank is rotated in the direction of the arrow, the arms 305 will lift, moving upwardly and outwardly about their pivot on the shaft 301. This will cause pins 306 to move upwardly in slots 307, swinging the arms 298 outwardly and moving plate 296 away from the contact with the edges of the strips at the assembly position. Movement of the crank in the opposite direction will cause a reverse movement of the parts and bring the plate into its strip-engaging position. The parts are normally urged toward the strip-engaging position by a spring 312, secured to the center arm 304 of the bellcrank and to an anchor 313 mounted on the rail 239. The bellcrank is moved by means of a control rod 314, connected at one end to the arm 304 of the bellcrank and having its opposite end slidable in a support 315 fixed to the top bedplate 280 of the table. The outer end of the rod carries a striker knob 316 which is engaged by a lug 317 by the inserting plate assembly.

When the inserting plate 294 moves transversely of the machine, it pushes the gathered long strips 2 through the spaces between the bedplates of the table into assembled relation with the gathered strips 3 at the assembly position. As the inserting plate pushes the strips into fully assembled position, the ends of the interlocking slots of the two sets of strips come into engagement, so that any further movement of the inserter plate will tend to push the assembled pack transversely. At this time, the lug 317 engages striker knob 316 and moves control rod 314 to rock the bellcrank lever. This causes the retaining plate 296 to move out of engagement with the assembled pack and free the pack for discharge from the machine. As the retaining plate moves away from the pack, continued movement of the inserting plate pushes the pack in the direction of movement of the plate until the spread flaps of the partition strips 3 are free of the guiding lips, or ledges, on the edges of the bedplates, at which time the assembled pack will be free and drop vertically from the assembly position onto a suitable receiver (not shown). The assembled packs can be manually removed from the receiver, or the receiver could be of the type which would automatically convey the assembled packs to a storage point.

Referring now to that form of the invention shown in FIGS. 34 through 36, there is shown another modification of the machine wherein the short partition strips 3 are assembled in the same manner as before, but by slightly different

mechanism, while the long strips 2 are fed from three separate magazines at three separate levels, each magazine feeding single sheets to one of the several spaces between the bed plates of the machine table. The assembly of the gathered groups of strips into a completed inner pack follows the same

The machine is mounted upon a frame having legs 318 which support longitudinally extending tubular beams 319. The beams are joined at their ends by end plates 320, and the end plates support a table 321, which basically, is the same as those previously described.

As mentioned above, the short strips 3 are supplied from a magazine, picked up by a gathering bar, transferred to a position for assembly, and moved into that position and held in that position with the flaps between the slits in strip edges being held in vertically spaced relation to provide the tapering throats for entry of the long strips 2, in substantially the same manner as in the previous forms. The mechanism for accomplishing this is best shown in FIGS. 35-A, 38, 39, 40 and 43.

In order to provide for the assembly of strips of various widths, the table 321 includes a movable rail 322, supported upon the end plates 320, and fixed to those plates by means of bolts 323 that pass through slots 324 in the rail 322 and into the end plates. By loosening the bolts, the plate can be adjustably positioned and then held in desired positions of adjustment.

A magazine 325 for short partition strips 3 has a sidewall 326 that is supported by brackets 327 mounted on the rail 322. This permits the sidewall to be adjusted with the rail 322. The magazine also has a fixed sidewall 328, mounted on brackets 329 secured to one of the tubular beams 319 (See FIG. 40). Sidewall 328 carries strip guides 330, 331, and 332, which are similar to the guides previously described, and are adjustably fixed to the wall by means of bolts passing through slots 333 in the wall 328. As the guides are substantially the same as those in the previous forms, no detailed explanation is needed.

Partition strips are taken from the supply in magazine 325 by means of a gathering bar 334. The gathering bar carries a plurality of pickup lugs 335, spaced along the bar at proper positions to pick up strips from the magazine in desired spaced sequence for positioning at the assembly position. The gathering bar is mounted upon a carriage 336 movable along rails 337 supported beneath the movable rail 322. Each of the pickup lugs of the gathering bar carries a microswitch 338 which has an actuating arm 339 positioned to contact the trailing end of the bottom strip in the magazine 325 as the lug moves to pickup position. Thus, each switch will be actuated as the lug engages the bottom strip of the pile in the magazine to move that strip from the magazine. The purpose of the switch and its operation will be described later in connection with the overall circuit.

The gathering bar is operated by means of a motor 340, mounted on the frame and carrying a crank 341. The crank is connected by a link 342 to a rocking lever 343 pivotally mounted at its bottom to the frame (See FIG. 36). The top of the lever 343 is connected by a link 344 to the carriage 36 of the gathering bar. Rotation of crank 341 will cause oscillation of lever 343 to move the gathering bar back to its pickup position and then forward through the magazine to pick up a group of partition strips and move them to the assembly position.

The longitudinal strips are supplied from three separate magazines, the magazines being in longitudinal alignment and in spaced, parallel relation to the magazine 325 and the feed path for the short partition strips 3. The magazines and the mechanism for feeding the long partition strips 2 can best be seen in FIGS. 34-A and 34-B, 35-A and 35-B, 40, 41, 42, 44 and 45.

Table 321, at the long strip side of the machine, is composed of a relatively short, top bedplate 345, a longer, next-to-top, intermediate bedplate 346, a still longer, next-to-bottom, intermediate bedplate 347 and yet longer, bottom bedplate 348. The several plates are supported from the end plates of

the frame and also from a side frame plate 349 carried by one of the tubular beams 319. The plates lie horizontally, in vertically spaced relation, with the spacing between the plates being sufficient to permit the passage of a partition strip, similar to the arrangement in the previously described embodiments. In this form, however, each strip is to be fed directly to its space between the plates, and, therefore, each of the three magazines 350, 351 and 352 is mounted on the plate which forms the bottom of the space into which the strips from that magazine are to be fed. Under this arrangement, magazine 350 is located to the next-to-top, intermediate plate 346, magazine 351 will be mounted upon the next-to-bottom, intermediate plate 347, and the magazine 352 will be mounted on the bottom plate. Top plate 345 extends from the discharge end of the machine to the magazine 350. The various bedplates have the various stop members between them and are adjustable as in the earlier embodiments.

Each magazine includes back support walls 353, and adjustable front walls 354 to permit adjustment for strips of different width. There is also an end wall 355 at the leading end of the strips, which wall is mounted upon the surface of the next higher adjacent bedplate. This leaves the space between this plate and the one on which the magazine is mounted open, so that the bottom strip in the pile can be advanced into the space.

Partition strips 2 are fed from the magazines 350, 351 and 352 by independent feeds, which are two-part mechanisms, including an escapement device for preliminarily moving the bottom strip from the pile to a friction wheel feed mechanism that completes the withdrawal of the bottom strip from the magazine and feeds it along the path to the assembly position. As the feed mechanism at each of the three magazines is identical, only one will be described and the same reference numerals will be applied to all three.

The escapement mechanism will be described first, and it is best seen in FIGS. 34-A and 34-B, 35-A and 35-B, 44 and 45.

The escapement mechanism 356 is mounted upon a support plate 357 fixed to, and held in, parallel spaced relation from the frame sideplate 349 by means of mounting blocks 358. Plate 357 carries a motor 359, supported on the outside of the plate, and the motor has a shaft 360 which projects through an opening 361 in the plate 357 and carries a cam 362, located in the space between the support plate 357 and the machine frame sideplate 349. An escapement lever 363 is pivotally attached at 364, near the bottom of the support plate 357. The lever is in the shape of a dog leg, and has a slot 365 near the juncture of the two angular sections of the lever to receive a drive pin 366 carried by the cam 362. The drive pin is located outwardly of the center of the cam, so that it acts as a crank to give an oscillating movement to the lever as the cam rotates. Lever 363 carries a pusher dog 367 at its top to engage, and push, the bottom strip from the supply in the magazine. Dog 367 extends horizontally inward from the top of the escapement lever to lie, and move, in the path of the bottom strip in the magazine. Rotation of the cam 362 will cause the lever to move forward to contact the bottom strip in the supply pile and push it forward into engagement with the friction wheel to be described.

Cam 362 of the escapement has a cam lift 368 that contacts, and operates, a microswitch 369 mounted on the support plate 357. This switch forms part of the control circuit, and acts as a limit switch for the escape mechanism to ensure stopping of the escapement mechanism with the pusher dog 367 in its inactive position.

The friction feed mechanism 370 is mounted upon a bracket 371 carried by the frame sideplate 349. This mechanism is best illustrated in 34-A and 34-B, 35-A and 35-B, 40, 41 and 42.

A motor 372, mounted on the bracket 371, supplies the power for the friction feed mechanism. A motor shaft 373 projects inwardly from the motor and carries a friction feed wheel 374. The feed wheel is located within a cutaway portion 375 of the next higher adjacent bedplate to the one on which the

magazine with which the friction feed is associated is mounted. The bottom surface of the wheel is positioned just above the plane of the top surface of the bottom partition strip in the magazine as it moves from its position in the magazine into the space between the bedplate on which the magazine is positioned and one just above it. Consequently, the feed wheel will not contact the surface of the strip being ejected from the magazine by the escapement mechanism, unless some means is provided for raising the strip into contact with the friction wheel.

A pressure bar 376 is provided to lift the advancing partition strips into frictional contact with the feed wheel 374. This bar is pivotally attached at one end, as at 377, in a bracket 378 fixed to the machine frame sideplate 349. The pressure bar lies outside of the sideplate 349 throughout its full length, but it has a pressure tongue 379 which projects inwardly into a cutaway opening 380 in the table bedplate upon which the magazine is mounted to underlie the friction feed wheel 374. The tongue has an arcuate upper surface 381 to insure smooth passage of a partition strip over the pressure bar as the strip is moved outwardly by the escapement. The pressure bar is raised to operative position by means of a solenoid 382 mounted on a bracket 383 fixed to the sideplate 349. A link 384 depends from the solenoid and passes through an opening in the pressure bar 376. The bar is yieldingly supported from link 384 by means of a spring 385 that encircles the leg beneath the bar and is held in position by a nut 386. This construction allows the solenoid to raise the bar, but permits the bar to yield downwardly to accommodate the thickness of the partition strips.

The operative throw of solenoid 382 lifts the pressure bar so that its tongue 379 moves into a position beneath the friction wheel, leaving a space between the tongue and the wheel which is slightly less than the thickness of the partition strips. This is done for two purposes. By having the tongue spaced less than the thickness of the partition strip from the friction roller, a pressure contact between the friction roller and the partition strip is assured. At the same time, the pressure bar can be used to operate a switch 387 mounted on the bracket 383 as the bar is lifted, and then to deactivate the switch as the pressure bar moves down under the influence of a partition strip moving between the bar and the friction wheel. This enables precision control of the feed mechanism as will be later described.

The feeding of the long strips 2 is accomplished by first pushing the bottom strips partially out of the magazines by operation of the escapement 356, and then completing the feeding of the strips into their spaces between the bedplates by means of the friction feed wheels. As the several magazines are located at different distances along the table from the point where the strips 2 are assembled for insertion into the group of strips 3 at the opposite side of the table, it is necessary for at least two of the magazines to feed more than one strip in order to have strips 2 at the position for assembly. Therefore, in starting up the machine, strips will be advanced from those magazines remote from the assembly point until a strip reaches one of the abutments 388 (See FIG. 35-A) which properly locate the strips in staggered relation for assembly with strips in the other group. As one strip is fed from the magazine, it will be pushed forward by feeding of the next successive strip. This process will be continued until the channels from the magazines to the assembly point are filled.

When a gathered group of strips 3 have been positioned at the assembly point in vertically spaced, angular position, with the edges of the slits spread as previously described, and a gathered group of long strips 2 are in horizontal, vertically spaced, staggered relation in position for assembly, the gathered group of strips 2 is moved across the table into assembly with the gathered group of strips 3 by means of an inserting mechanism 383. This mechanism is best shown in FIGS. 34-A, 35-A, 36, 37 and 38.

The inserter mechanism includes a plurality of inserter blades 390, one for each of the three spaces between the

bedplates of the table, with the blades being staggered in the same order as the partition strips to be inserted. The inserter blades are supported upon a carriage 391, mounted upon rails 392, fixed to supports 393, carried by the top bedplate and a spacial support 394 which is connected to one of the tubular beams 319. The inserter blades are caused to move between the bedplates by means of a link 395 connected to the inserter carriage 391 and to an arm 396 of a bellcrank 397. The bellcrank is pivotally mounted on a strut 398 projecting from one of the legs 318 of the frame. The other arm 399 of the bellcrank is connected to a second link 400 that has its opposite end connected to the free end of a lever 401, pivotally mounted at 402 on the frame. Lever 401 is caused to rock in a vertical plane by means of a cam 403 mounted on the shaft of the motor 340 that drives the gathering bar for the group of partition strips 3. The cam has a high lobe 404, oriented with respect to the crank 341 that operates the gathering bar to be operative to lift the lever 401 and move in the inserter blades 390 forwardly at such time as the gathering bar is at the phase of its stroke adjacent the magazine 325, so that the gathering mechanism is completely out the way when the inserter blades are moving. Lever 401 is caused to maintain firm contact with the cam to return to its lower position as the cam permits it, by means of a spring 405 attached to lever 401 and to the frame.

When a group of partition strips 3 are at the assembly position, their slit edges are in the guides on the bed plate edges with their opposite, unslit edges in abutment with a retaining plate 406, similar to the retaining plate in the form just described. The retaining plate is mounted similar to the previous one, as it is supported by a plurality of arms 407 mounted upon a pivot shaft 408 journaled in the upper ends of mounting pedestals 409 fixed to the movable rail 322. One of the arms carries a small plate 410 having a control slot 411. A pin 35 412, carried by one arm 413 of a bellcrank 414, fits within the slot and is movable within the slot as the bellcrank and arms move. The bellcrank is pivotally mounted at 415 in brackets 416 fixed to the movable rail 322. A spring 417 is also attached to the bracket 416 and has its other end connected to the second arm 418 of the bellcrank 414. The spring serves to bias the bellcrank in a counterclockwise direction, as viewed in FIG. 37, to maintain pin 412 in the bottom of slot 411 to hold the retaining plate 406 in position for contact by the back edges of the partition strips 3 at the assembly position. Bellcrank arm 418 carries a roller 419 which is in the path of movement of a striker 420 on the link 395 extending from the bellcrank 397 to the inserter carriage 391. The striker is mounted on the link in such position to contact roller 419 at about the time the inserter blades 390 have completed the assembly of the partitions making up the inner pack. This will cause the bellcrank 414 to be rocked, and draw the arms 407 and the retaining plate 406 away from the assembly position. Because of this, the assembly may be moved as a unit in a horizontal direction to clear the edges of the flaps of the strips 3 from the guides on the edges of the table bedplates and permit the assembly to drop from the machine onto a suitable receptacle. As the inserter mechanism returns to its inoperative position, spring 417 will return the bellcrank and the retaining plate 406 into operative position.

That form of the invention shown in FIGS. 34 through 46 is electrically controlled and automatic in its operation after certain manual operations are performed in starting up the machine to gather groups of partition strips and position them at their respective assembly positions ready for insertion and assembly. The electrical control circuit is shown in FIG. 46. The circuit is shown in condition for automatic operation, as it will be when groups of partitions have been gathered and the two groups are at their respective positions ready for assembly.

When the machine is to be started up, suitable supplies of partition strips must be in the magazines 325, 350, 351 and 352. The circuit includes a powerline 421 and a return line 422, and a main switch 423 controls power to the machine. In starting up the machine, main switch 423 will be closed, and

an automatic manual switch 424 will be moved to its manual setting. This sets up a circuit from the powerline 421 through line 425, switch arm 426 of the switch 424, line 427, manual switch 428, lines 429 and 430, and motor 340 to return line 422. When switch 428 is closed, motor 340, which is the motor operating the gathering mechanism for the short partition strips 3 from magazine 325, is energized to cause the gathering mechanism to move through one cycle of its operation. As gathering bar 334 begins to move, its microswitches 328, which were in the opposite position to that shown on the diagram in FIG. 46, will be actuated in succession as the gathering lugs contact the partition strips in the magazine 325. Switches 328 are connected in series in a circuit which includes powerline 421, line 431, the five switches 328, line 432, cam controls switch 433, warning light 434, line 435, normally closed contact 437 of relay 438 and line 439 to the return line 422. Control cam 433 is on the shaft of motor 340 and revolves with that shaft. When switch 428 is closed, and the motor starts, cam 433 will begin to rotate and allow switch 433 to open, extinguishing the warning light 434. The light will remain out during the remainder of one cycle of operation of the motor 340, at which time the cam of switch 433 will have returned to its original position closing the switch. If any of the switches 328 have remained closed, a circuit will be completed through the warning light and the light will be turned on. This indicates that there is not a proper positioning of the group of strips 3 at the assembly position. If all of the switches 328 have been actuated, light 434 will not come on. At the same time that cam control switch 433 begins to move, a similar cam control switch 440, the cam which is also on the shaft of motor 340, will start to move. This will close a circuit from the power line 421 through wire 441, switch arm 442 of the control switch 440, line 443 to lines 429 and 430 and motor 340 to return line 422. This establishes a circuit through motor 340 not controlled by the manual switch 428. Therefore, as soon as cam switch 433 opens and light 434 goes out, the operator may release switch 428. The motor will continue to operate through one complete revolution of its shaft, at which time the cam of the control switch 440 will again operate to break the circuit at 422, shutting off the motor. This occurs at the same time that cam switch 433 is again in closed position. As mentioned above, if the light 434 does not again come on, a full supply of strips 3 have been moved to the assembly position.

The operator will then manually close the three switches 444 in parallel circuits including the friction feed motor 372. These circuits include the powerline 420, parallel lines 445, switches 444, motors 372 and line 446 to return line 422. These motors run continuously during the operation of the machine to keep the friction feed wheels 374 in constant rotation.

With all of the switches 328 in the position shown in the diagram, and the remaining three switches in that line being in their opposite position to that shown, a circuit will be completed from the power line and through the switches 328 to a switch 447, line 448, warning light 449, line 450, line 435, normally closed relay contact 437 and line 439 to the return line 422. Thus, warning light 449, which is the warning light for magazine 350, will come on as soon as all of the switches 328 have been closed. This will indicate that the machine is now ready to position the first of the long partition strips 2.

The operator next closes load switch 451 which energizes solenoid 382, associated with the long partition strip magazine 350. This circuit includes the powerline 421, wire 425, switch arm 426, wire 427 to wire 452, wire 453, load switch 451, which now is in contact with line 453, line 454, and solenoid 382 to return line 422. Energization of solenoid 382 will draw up pressure bar 376, closing switch 383 and completing a circuit to the associated motor 359 of the escapement mechanism. This circuit includes the portion of the circuit last described through the load switch 451, line 454 to line 455, switch 383, line 456, motor 359 and return line 422. This will start the escapement motor and oscillate escapement lever

363, moving dog 367 into engagement with the bottom strip in magazine 350. As the strip moves forward between the friction wheel 374 and the pressure bar 376, it pushes down the pressure bar, allowing switch 383 to open. By this time, the motor operation has caused cam 362 on the motor shaft to open switch 369, so that motor 359 will remain stopped unless restarted by closure of the switch 383. As it may require more than one strip to fill the channel between the magazine 350 and the position of rest of its strips between the top two bedplates of the table, continued closure of the switch 451 will again draw up the pressure bar 376, as soon as the first partition has passed between it and the friction wheel, and again operate the escapement mechanism to feed a second strip. This will continue until the first strip fed from magazine 350 strikes switch 447, which is located at the assembly position for the strips from magazine 350. When this happens, switch 447 closes and light 449 goes out. Immediately, light 457 for magazine 351 will come on, as its switch 458 is the first in the series line of microswitches to be in open position. Wire 459 leads from the switch to the light, and wire 460 goes from the light to line 435.

When light 457 comes on, the operator can then close a load switch 461 to energize solenoid 382 of the magazine 351. As this is a parallel circuit to the one just described, a detailed description is not thought necessary. The operation of switch 461 will energize the solenoid, pull up the pressure bar and energize the motor 359 of the escapement at magazine 351 to eject strips from that magazine. This motion will continue until the intermediate space between the bedplates of the table is filled, and switch 458 is struck by the leading strip and moved to the position shown in FIG. 46. Light 457 will then go out and warning light 462 for the magazine 352 will come on. Switch 463 controlling light 462 is the only one now in contact with its lead 464, so that current can come from the powerline through the switches to switch 463 and through line 464 to light 462.

The remaining load switch 465 will then be closed to energize its solenoid 382, and to start the action which will cause the escapement to operate and feed strips from magazine 351. This switch will be maintained in closed position until the lowermost space between the bedplates of the table is filled and the leading strip from magazine 352 reaches the end of its travel and strikes, and closes, switch 463, causing light 462 to go out. All of the partition-actuated switches have now been moved to complete the series of closed switches completing a circuit to a machine start button 466 by means of line 467. As the warning lights are now out, indicating that all partitions are in position ready for assembly of the inner pack, the machine is now ready for automatic operation.

With the parts in the position just described, the operator will move the switch control 424 from manual to automatic to break the circuits originally established through contact 426, and establish a circuit through the automatic contact 468. The machine is now ready to start, and the operator will close the start button 466. This will establish a circuit from powerline 421 through the series of partition operated microswitches, line 467, start button 466, line 469, automatic contact 468, line 470, relay 438 and line 439 to return line 422. This will energize relay 438, open normally closed contact 437 and close normally open contacts 471, 472 and 473. As soon as contact 471 closes, a bridge circuit around the starting button 466 is established through wire 474 to maintain the relay in operation. Motor 340, operating the gathering bar for the short strips 3 is now in a direct circuit with the powerline 421 through a line 475, now closed by relay contact 472. Solenoids 382 and escapement motors 359 now receive power directly from powerline 421 through line 476 and now closed relay contact 473. There is a cam-actuated switch 477 in this line, which is mounted on the motor shaft 340 and operates through half of its cycle to maintain the switch closed and half of its cycle to maintain the switch open. By having the cam properly timed with respect to the remainder of the operation, solenoids 382 can be deenergized during that portion of the

machine cycle when the gathered group of strips 2 are being transferred across the machine and inserted into the assembled group of strips 3, and the inserting blades return. By reason of this, the pressure bars 376 will be lowered and the partition at the feed position will not be in contact with the rapidly rotating feed wheels 374.

Cam switch 440 has its switch arm 478 positioned to make contact with a line 479, that is tied in with the relay bridge circuit 474. The cam will operate once each revolution, at the time the two groups of gathered partition strips will have been moved into position for assembly, to open the line 479 so that the only line holding the relay in operation is the one which contains the plurality of partition-operated switches. If there is a malfunction and one partition is not in its proper place, one of the switches of the group 328, 447, 458 and 463 will be moved making contact with its respective light circuit. This will interrupt the circuit through line 457 so that the relay will be deenergized and the machine will stop. At the same time, the warning light for the particular magazine which has malfunctioned will come on to indicate the source of the trouble. If there is no malfunction, the cycle will continue to be repeated until such time as the operator depresses the stop button 480 in the line 467. This will break the circuit through line 467 to the relay, but it will not break the circuit through line 441 to the relay. Thus, the machine will continue in operation until it has finished its cycle of movement and the gathered groups of partition strips are at their position for assembly. At this time, cam 440 will operate to open switch 478 to break the only remaining circuit to the relay, whereupon the machine will stop. By having this safeguard, the machine will always stop with a full load of partitions ready for assembly.

Referring now to that form of the invention shown in FIGS. 47 to 52, the machine of this modification differs from the one just described principally in the manner of gathering the long partition strips 2 and positioning them for assembly with the gathered group of short partition strips 3. In other respects, it is very similar to the form just described.

The machine includes a frame 481 which has tubular side beams 482, as before, joined by end plates 483. A table 484 is mounted on the frame.

The table includes a movable rail 485, that is fastened to the end plates 483 by means of bolts 486 passing through slots 487 in the rail. This permits the rail to be moved in and out for purposes of adjustment as in all of the previous forms. There is a magazine 488 for short strips 3 and the rail carries one wall 489, while the other wall 490 is fixed to the frame and supports the strip guides 491. These guides are the same as those of previous forms, and serve to support the partition strips 3 in the magazine and to incline and guide the strips as they move from the magazine to the assembly position. All of this structure is similar to the previous forms and is not shown, nor need it be described, in detail. The strips are gathered from the magazine in predetermined staggered relation by means of a gathering bar 492 (shown in dotted lines in FIG. 47 and in end elevation in FIG. 48) and moved by the gathering bar to the assembly position. Each of the pickup lugs of the gathering bar carries a microswitch 493 (See FIG. 48) identical to the microswitches of the form just described.

The gathering bar is operated by means of a motor 494, a crank 495, pivoted lever 496, and line 497 from the lever to the gathering bar, exactly as in the form just described. Rotation of the motor turns the crank, oscillates the lever and moves the gathering bar back and forth to bring partition strips from the magazine 488 to the assembly position and return.

There are three magazines for the long strips 2. There is a central magazine 498, a magazine 499 to the left, as viewed in FIGS. 47, 49-A and 51, and a magazine 500 to the right. The magazines 499 and 500 are in longitudinal alignment while the center magazine 498 is forwardly displaced relative to the other two magazines.

The three magazines are mounted on separate bedplates of the table 484. There are four bedplates, held in spaced rela-

tion to permit the free movement of partition strips between them, as in the previous forms. The bottom bedplate 501 supports the partition strips in the magazine 499, and the magazine is mounted upon the bottom plate at one side and the next-to-bottom plate 502 at the other side. This permits strips ejected from the magazine 499 to move through the space between the bedplates 501 and 502. Magazine 500 has its partition strips resting upon the top of the next-to-bottom bedplate 502, and the magazine is mounted upon the plate 502 at one side and the top plate 504 at the other side. Its partition strips, when ejected, move in the space between the bedplates 502 and 503. The center magazine 498 is mounted upon the top bedplate 504, but the strips within it rest upon the next-to-top bedplate 503. This permits strips from this magazine to move in the space between the bedplates 503 and 504.

It will be noted that the top plate 504 and the plate 503 immediately beneath it are quite short, and lie wholly between the magazines 499 and 500. Bedplate 502 extends from the magazine 500 to the opposite side of the magazine 499, while the bottom bedplate 501 extends from the magazine 499 to the opposite side of the magazine 500. Thus, no provision is made for movement of the partition strips from the magazine 498 longitudinally of the machine, but the spaces between the bedplates in which the strips from magazines 499 and 500 move extend from the respective magazines longitudinally of the machine to positions beneath the magazine 498, but staggered with relation to the strips in magazine 498 and with respect to each other, (See FIG. 51). This positions the strips of the three magazines in proper vertically spaced, longitudinally staggered position for assembly with a gathered group of strips from the short strip magazine 488.

Strips are picked up from the magazines 499 and 500 and moved in opposite directions from the magazines to the gathering point. This is accomplished by means of pickup lugs 505 and 506 which are mounted on carriages 507 and 508, traveling on rails 509 and 510, respectively. The rails are mounted upon the tubular beam 482 immediately below the magazine position.

The carriages are connected to cables 511 and 512 which control the movement of the carriages. The cables are fastened, respectively, to reels 513 and 514, journaled on shafts 515 and 516 at opposite ends of the frame. Springs 517 and 518 are mounted on the shafts 515 and 516, and each has one end fixed to the reel on the shaft and the other end fixed to the shaft, so that rotation of the reel in an unreeling direction will wind the spring. Therefore, when the cables are drawn out, the reels will automatically rewind them as the pull on the cables is released. The cables are dead-ended on the reels and extend from the reels to the carriages, and from the carriages over pulleys 519 and 520. Their opposite ends are dead-ended in a clevis 521 attached to the outer end of a crank 522. Crank 522 is mounted on a shaft 523 journaled in a bracket 524 (See FIGS. 48 and 49-A) depending from the frame 481. Crankshaft 523 carries a gear 525 which meshes with a gear 526 on the shaft 527 of a motor 528, also mounted on the bracket 524. Operation of the motor will cause rotation of crank 522, which will alternately draw out the cables 511 and 512 to move the carriage 507 and 508 forwardly to eject the bottom strips of the magazines 499 and 500 move them to their gathered position beneath the magazine 498, and allow the cables to be retracted by the springs on the reels 513 and 514 to return the carriages to their positions of rest. As the crank moves toward its downward position, shown in full lines in FIG. 49-A, the cables will be drawn from the reels, and as the crank moves upward the reels will take up the cable as described.

When strips 2 from the magazines 499 and 500 have been gathered beneath the magazine 498, and the carriages begin their return movement, an injecting mechanism 529, similar to the injecting mechanism for the previous forms, will start its operative movement to push the gathered strips below the magazine 498 together with the bottom strip in the magazine

498 transversely of the table into assembled relation with gathered group of strips 3 at the assembly position. The injecting mechanism includes a carriage 530, movable on rails 531 mounted on supports 532 on the top bedplate 504, and a support 533 mounted on a bracket 544 fixed to the frame. The carriage mounts three inserter blade 535 which are movable through the spaces between the 544, bedplates. The carriage is moved by a bellcrank 536 connected to a carriage-operating rod 538. The rod is offset by means of a bracket 539 to one side of the assembly position to locate the rod at the side of the center magazines 498. Bellcrank 536 is operated by a cam 540 on the shaft of the motor 494 which operates the gathering bar for the short partition strips 3. This connection, and operation, is precisely the same as in that form of the invention just previously described and will not be referred to in detail.

The gathered strips at the assembly position are held in proper place pending assembly means of a retainer plate 541 mounted on pedestals 542 and controlled by a bellcrank 543 as in previous forms. The offsetting bracket 539 on the inserter carriage operating rod carries a striker rod 544, having a striker 545 on its end to contact and operate the bellcrank to shift the retaining plate and allow the assembled inner pack to drop from the machine, in the same manner as in several of the preceding forms.

This form of the machine is controlled by an electrical system which is similar, in most respects, to the control circuit, shown in FIG. 46. It does however, differ from that circuit in minor degree, due to the difference in machine operating mechanisms.

The circuit includes powerline 546 and a return line 547. Microswitches 493 on the gathering bar 492 are arranged in series in a line 548 from the powerline as before. They, when inactive complete a circuit through wire 549, cam switch 550, warning light 551, line 552, normally closed relay circuit 553 and lines 554 and 555 to the return line 547. This is an identical circuit to the one which controlled the warning light for the magazine for the short partition strips 3 in the previously described form. If any of the switches 493 are closed with the line 549, the light 550 will be on to indicate that partition strips are not properly positioned. When all of the switches are closed with the line 548, the light will be out, indicated that partitions are properly positioned. Switches 556, 557 and 558 are in series in the line 548 also, and through line 559, 560 and 561, control the warning lights 562, 563 and 564 of the long partition strips magazines 498, 499 and 500. Here, again, the arrangement is the same as in the previous circuit. Switches 557 and 558, for the warning lights 563 and 564 of the magazines 499 and 500, will be located between the bedplates of the table in the spaces through which the partition strips from those magazines move to be contacted by those strips when they arrive at the gathered position, as was the case in the previous form. The switch 556 for the warning light 562 of the magazine 498, however, will be located at the bottom of the magazine to be operated by strips within the magazine. Thus, while the warning lights 563 and 564 indicate the presence of partition strips at the gathered position, the warning light 562 indicates a supply of strips in the magazine, with the bottom strip being ready for ejection and insertion with the other strips.

In operating this system, it is also necessary that the device be run through manual operations to load partition strips at the points for assembly prior to starting the automatic cycle. In order to do this, it is necessary that an automatic manual switch 565 be moved from the position shown to the left to the manual position. This will cause the manual control switch arms 566 and 567 to close with their respective contacts, and the automatic circuit arm 568 to open the automatic line.

With the manual switch in the position just described, load switch 569 can be depressed to energize motor 494 of the gathering mechanism for the short partition strips 3. This circuit will include powerline 546, wires 570, 571, switch arm 566, load switch 569, lines 572, 573, 574 and 575, motor 494 and line 576 to the return line 547. When this circuit is

completed, the gathering bar will commence its operation. As soon as the motor begins to rotate, cam 550, which is on the motor shaft, will open the cam switch and light 551 will go out. At the same time, cam 577, also on the motor shaft, will rotate and close its contact arms 578 and 579. Therefore, as soon as light 551 goes out the load switch 569 can be released, as there will be a motor circuit 569 from powerline 546 through wire 570, switch arm 579, wire 572, wires 573 and 574 and 575, motor 494 and line 576 to return line 547. Thus, the motor will continue to operate until cam 577 makes a full revolution of move the contact 579 and open the circuit. At this time, the gathering bar will have gathered its group of partition strips 3 and moved them to the assembly position. At the conclusion of the cycle of operation of the motor, cam 550 also closes, but if all of the partitions are in place the switches 493 will be closed in line 548 so that light 551 will not be illuminated. This will indicate that the short partitions are in proper place.

The operator will then close load switch 580 to energize the motor 528 and advance the longitudinal strips to their proper position for assembly. Closure of switch 580 completes a circuit from powerline 546, line 548, the now closed five switches 493, line 581, closed manual switch 567, line 582, load switch 580, line 583, line 584, motor 528 and return line 547. This will cause the motor 528 to begin its operation to move partition strips 2 from the magazine 499 and 500 to positions beneath the magazine 498. As this occurs, switches 557 and 558 will be closed causing lights 563 and 564 to go out. It will be remembered that switch 556 is operated by the stack of partitions in magazine 498 so that this switch will be closed and light 562 will be extinguished also if a supply of strips is in magazine 498. As soon as the lights go out, switch 580 can be released. By this time, cam switch 586 will have closed, so that a circuit is maintained through the motor from power line 546, line 548, line 581, switch 567, line 552 to line 585, switch 586, lines 587 and 584, motor 528 and return line 547. Thus, motor 528 will continue to operate, even though switch 580 is released, until such time as the cam of cam switch 586 operates to break the circuit at that point. When this occurs, motor 528 will cease operation.

When the above operations have been completed, the lights 551, 562, 563 and 564 should all be extinguished indicating that partitions are at the proper positions ready for the assembly of the group of long partitions 2 with the group of short partitions 3 at the assembly point. Switch 565 can now be moved to its automatic position, which breaks the circuit through switch arms 566 and 567 and closes the circuit through switch arm 568. The machine is now ready to be put into automatic operation.

When the machine is to be started for automatic operation, start button 588 is depressed. This closes a circuit from powerline 546 through line 548, this closed switches 493, 556, 557 and 558, wire 589, start switch 588, line 590, switch arm 568, line 591, line 592, relay 593 and line 555 and return line 547. This will energize the relay, closing its contacts 594, 595 and 596. The normally closed contact 553 will open. When the relay is energized, a circuit will be completed to motor 494 through powerline 546, line 570, line 571, line 597, closed relay contact 595, wire 575, motor 494, line 576 and return line 547. This will start operation of this motor. At the same time, the closing of the relay switch 596 completes a circuit from powerline 546, contact 596, line 585, cam switch 586, lines 587 and 584, motor 528 and return line 547.

With the operation of the relay and the closing of contact 594, a bypass circuit around the start button 588 is closed. This circuit includes the powerline 546, line 570, contact 578 of the cam switch, line 598, relay contact 594, line 590, switch 70 contact 568, line 591, line 592, relay 593 and line 555 to return line 547. This operates to keep the relay in operation after start button 588 has been released. The original relay circuit through line 589 now bridges the start button through line 598 and relay contact 594, to maintain the relay in operation. In exactly the same way as with the former circuit cam 577

acts once each revolution to open its contact 578 so that if any of the switches 493, 556, 557 and 558 are open the entire circuit to the relay will be broken, and the relay will move to its inoperative position breaking the circuits to the motor 494 and the motor 528.

In the event that relay 593 is deenergized by the opening of any of the switches 493, 556 and 558, motor 494 continues to operate through its full cycle by means of a circuit from powerline 546, line 570, switch arm 579 operated by cam 577, line 599, lines 573, 574, 575, motor 494 and line 576 to return line 547. As switch arm 579 is operated by the cam 577, it will not be opened until the end of the cycle of operation of motor 495. Therefore, switch arm 579 acts as a limit switch for the motor cycle. Motor 528 also has a limit switch 600 which is bridged across the lines 591 and 587 to maintain the motor in operation after switch 586 opens following starting of the motor. This shifts the power to the motor, from the line 546 through relay contact 596, to the circuit through the automatic contact 568 of the main switch 565.

Once the operation of the automatic system has begun, the machine will continue to gather strips of the two groups and bring them together into assembled form. When it is desired to shut down the operation of the machine, a stop button 601 is pressed to break the circuit to the relay. The machine will not stop, however, until the motors have reached the end of their cycles of movement.

While four different embodiments of the invention have been disclosed, the same basic concept of operation is embodied in all. In each one, a group of short partition strips 3 is gathered from a magazine into vertically spaced, longitudinally staggered, inclined position and moved to a station for assembly. Long partition strips 2 are ejected from one or more magazines and moved longitudinally of the machine to a position transversely opposed to the first group. The strips 2 are arranged in vertically, spaced, longitudinally staggered relation. In all cases, the slit edges of the two groups of strips are in facing relation, and the bridges of the slits of the short strips are vertically spread to receive the strips 2 of the second group. The gathered strips 2 are moved transversely of the machine into the gathered group of strips 3 at the assembly position. The assembled inner packs are then suitably discharged from the machine. The difference between the several embodiments of the machine lie in the magazines for feeding the several strips, their location, and the means for gathering the strips from the magazines.

Although several embodiments of the machine have been disclosed, it will be understood that these are merely by way of illustration and that the basic handling of the strips to form opposed groups and bring the groups together in assembled relation may be carried out by other specific means.

What is claimed is:

1. A method for assembling partition strips, slit inwardly at predetermined intervals along one edge forming a plurality of flaps, into interfitting angular relation to form inner packs for use in crates, cartons and the like comprising the steps of, gathering partition strips from sources of supply into two groups, arranging the partition strips of a first group in vertically spaced, longitudinally staggered relation, arranging the partition strips of a second group in vertically spaced, longitudinally staggered relation, moving the two groups of partition strips of the two groups into opposed relation with the slit edges of the partition strips of the two groups in confronting relation and the plane of the partition strips of one group at an angle to the plane of the partition strips of the other group, moving the flaps of the partition strips of one group vertically to diverge the sides of the partition strip slits to form open throats, and moving the groups of partition strips together to cause the partition strips of one group to enter the open throats of the partition strips of the other group to form an assembled inner pack.

2. A method for assembling partition strips to form inner packs as claimed in claim 1 wherein, the partition strips of the first group are inclined relative to the strips of the second

group, the flaps of the first group are moved vertically and the partition strips of the second group are moved into the open throats of the partition strips of the first group.

3. A machine for assembling partition strips, slit inwardly at predetermined intervals along one edge forming a plurality of flaps into interfitting angular relation to form inner packs for use in crates, cartons and the like comprising, a frame, a table on the frame, means on the table to hold a supply of first partition strips, means on the table to hold a supply of second partition strips, means to gather a group of first partition strips from the supply and position them in vertically spaced, parallel, longitudinally staggered relation at an assembly position on the table, means to gather a group of second partition strips from the supply and position them in vertically spaced, parallel, longitudinally staggered relation at a position opposed to the assembly position, with the slit edges of the partition strips confronting relation and the partition strips of one group at an angle to the partition strips of the other group, and means to move the groups of partition strips together and interengage the slits of the partition strips of one group with the slits of the partition strips of the other group to assemble an inner pack.

4. A machine for assembling inner packs as claimed in claim 3 wherein, there are means to engage the flaps of the partition strips of one of the gathered groups and vertically separate the flaps as the partition strips of that group are moved from the means to hold a supply to the assembly position, and means at the assembly position to hold the flaps in vertically separated position during the insertion of the partition strips of the other group to form the inner pack.

5. A machine for assembling inner packs as claimed in claim 4 wherein, there is means to discharge the assembled inner pack from the machine.

6. A machine for assembling inner packs as claimed in claim 3 wherein, the means on the table to hold a supply of first partition strips is a magazine, guides in the magazine along one wall having vertical legs and horizontal legs, the guides being equal in number to the number of slits in the first partition strips and having guide flanges projecting inwardly of the magazine to enter the slits in the first partition strips in the magazine to align the first partition strip in the magazine, the horizontal legs being vertically spaced to provide guide channels between them, the horizontal legs and the vertical legs joining to form ledges upon which the slit edges of the bottom one of the first partition strips may rest, the ledges being in inclined continuation of one another to hold the bottom first partition strip at an angle to the horizontal, and the means to gather a group of first partition strips engages the bottom first partition strip at the low end of the partition strip and pushes the partition strip lengthwise from the magazine, whereby the slits of the partition strip will separate vertically and the flaps of the slit edge will move in separate channels formed by the horizontal guide legs to position the flaps in vertically spaced relation as the partition strips move from engagement with the vertical legs the guides.

7. A machine for assembling inner packs as claimed in claim 6 wherein, the magazine is adjustable widthwise to accommodate partition strips of different depth, and the guides are movable longitudinally of the magazine to accommodate partition strips of different length.

8. A machine for assembling inner packs as claimed in claim 6 wherein, the means to gather a group of first partition strips includes a gathering bar having a path of movement beneath the magazine and to the assembly position, a plurality of lugs in the gathering bar in predetermined spaced relation to engage and pick up successive bottom first partition strips as the gathering bar moves beneath the magazine and carry them in parallel, spaced, angular position to the assembly position, and means to move the gathering bar from the magazine to the assembly position and return.

9. A machine for assembling inner packs as claimed in claim 3 wherein, the means to move the groups of partition strips together includes inserter blades to engage the respective vertically spaced second partition strips of the gathered group,

and means to move the inserter blades transversely of the table.

10. A machine for assembling inner packs as claimed in claim 3 wherein, the table has a plurality of vertically spaced bedplates forming a plurality of horizontal passages between them, the means to gather a group of second partition strips includes means to position a second partition strip in each of said passages and move the second partition strips longitudinally of the machine through the passages to the position opposed to the assembly position, and the means to move the groups of partition strips together includes inserter blades movable transversely of the machine through the passages, and means to move the inserter blades.

11. A machine for assembling inner packs as claimed in claim 6 wherein, the table has a plurality of vertically spaced bedplates forming a plurality of horizontal passages between them, the means to gather a group of second partition strips includes means to position a second partition strip in each of said passages and move the second partition strips longitudinally of the machine through the passages to the position opposed to the assembly position, and the means to move the groups of partition strips together includes inserter blades movable transversely of the machine through the passages, and means to move the inserter blades.

12. A machine for assembling inner packs as claimed in claim 11 wherein, the edges of the table bedplates adjacent the assembly position have horizontal ledges in continuation of the horizontal legs of the guides along which the flaps of the first partition strips ride to maintain the flaps in vertically spaced relation with each slit of the first partition strips spanning a passage between the table bedplates.

13. A machine for assembling partition strips, slit inwardly at predetermined intervals along one edge forming a plurality of flaps, into interfitting angular relation to form inner packs for use in crates, cartons and the like comprising, a frame, a table on the frame having a plurality of vertically spaced bedplates providing horizontal passages between the bedplates, a magazine for a supply of first partition strips, a gathering bar having a path of movement beneath the magazine in a direction longitudinally of the table and the magazine and to an assembly position on the table, means to move the gathering bar from the magazine to the assembly position and return, pickup lugs spaced along the gathering bar equal in number to a predetermined number of first partition strips to form a first group, means in the magazine and on the table to position strips gathered from the magazine at an angle to the horizontal, whereby first partition strips delivered by the gathering bar at the assembly position will form a first group with the first partition strips in vertically spaced, angular position, a source of supply of second partition strips on the table, means to gather second partition strips from the source of supply and move them to a position opposed to the assembly position in a second group of horizontal, vertically spaced partitions, and means to move the second group of partition strips into the first group of partition strips to assemble an inner pack.

14. A machine for assembling partition strips into inner packs as claimed in claim 13 wherein, the magazine has means to lift all first partition strips in the magazine above the bottom one to free the bottom one for pick up by the lugs of the gathering bar, and means on the gathering bar to operate the lift means prior to contact of each lug of the gathering bar with the bottom first partition strip in the magazine and maintain the lift means operative during ejection movement of the bottom first partition strip from the magazine.

15. A machine for assembling partition strips into inner packs as claimed in claim 14 wherein, the means on the gathering bar to operate the lift means are cams, and the lift means includes an operating member having a position on the path of movement of the cams.

16. A machine for assembling partition strips into inner packs as claimed in claim 15 wherein, there are means carried by the gathering bar to position the lift means operating

member in the path of movement of the cams at the end of a return stroke of the gathering bar and to position the operating member out of the path of movement of the cams at the end of a gathering stroke of the gathering bar.

5 17. A machine for assembling partition strips into inner packs as claimed in claim 13 wherein, the magazine has a supporting ledge along one side for the bottom first partition strip in the magazine, strip guides mounted on the opposite side of the magazine having portions to support the opposite side of the bottom first partition strip, and means to move the bottom first partition strip transversely toward the guides to free the strip of the support ledge.

15 18. A machine for assembling partition strips into inner packs as claimed in claim 17 wherein, the means to move the bottom first strip transversely has an operating member, and there are means on the gathering bar to the operating member prior to contact of each lug of the gathering bar with the bottom first partition strip.

20 19. A machine for assembling partition strips into inner packs as claimed in claim 18 wherein, the means on the gathering bar to operate the means to provide first partition strip transversely are cams, and the operating member has a position in the path of movement of the cams.

25 20. A machine for assembling partition strips into inner packs as claimed in claim 19 wherein, there are means carried by the gathering bar to position the operating member in the path of movement of the cams at the end of a return stroke of the gathering bar and to position the operating member out of the path of movement of the cams at the end of a gathering stroke of the gathering bar.

21. A machine for assembling partition strips into inner packs as claimed in claim 13 wherein, there are means to discharge assembled packs from the machine.

35 22. A machine for assembling partition strips into inner packs as claimed in claim 13 wherein, the gathering bar carries an inner-pack-ejecting means to contact and move an assembled inner pack from the assembly position as the gathering bar makes a gathering stroke.

40 23. A machine for assembling partition strips into inner packs as claimed in claim 13 wherein, there is a retaining plate at the assembly position for contact with the edges of first partition strips at the assembly position to hold the first partition strips into engagement with means on the table to hold the first partition strips at an angle to the horizontal, and means to retract the retaining plate.

45 24. A machine for assembling partition strips into inner packs as claimed in claim 23 wherein, the means to retract the retaining plate includes a retaining plate-positioning lever, and means carried by the means to move the second group of partition strips into the first group of partition strips to strike and operate the retaining plate-positioning lever.

50 25. A machine for assembling partition strips into inner packs as claimed in claim 24 wherein, there are means resiliently biasing the retaining plate to strip-retaining position.

55 26. A machine for assembling partition strips into inner packs as claimed in claim 13 wherein, the source of supply of second partition strips is a second magazine, means to eject second partition strips singly from the second magazine, and the means to gather and position a second group of partition strips includes means to arrange the ejected second partition strips in vertically spaced relation at the respective horizontal planes of the passages between the table bedplates and the means to move the arranged second partition strips to the position opposed to the assembly position.

60 27. A machine for assembling partition strips into inner packs as claimed in claim 26 wherein, the means to arrange the ejected second partition strips is an elevator located adjacent the second magazine and having shelves vertically spaced in the same order as the table bedplates, means to move the elevator vertically a distance of one shelf after each ejection stroke of the means to eject second partition strips from the second magazine and to position the elevator with its

shelves in the planes of the table bedplates following a predetermined number of second partition strips having been received in the elevator.

28. A machine for assembling partition strips into inner packs as claimed in claim 27 wherein, the means to move the arranged second partition strips to the position opposed to the assembly position includes a plurality of pusher arms staggered longitudinally of the machine and mounted for movement through the elevator shelves and into the passages between the table bed plates, and means to move the pusher arms when the elevator shelves are aligned with the table passages.

29. A machine for assembling partition strips into inner packs as claimed in claim 13 wherein, the source of supply of second partition strips is a plurality of second magazines mounted on the table with each second magazine having an outlet for second partition strips aligned with a passage in the table, and the means to gather and move the second partition strips to the position opposed to the assembly position including means to eject second partition strips from the second magazine into the table passages and move them to the opposed position.

30. A machine for assembling partition strips into inner packs as claimed in claim 29 wherein, the means to eject and move second partition strips includes an escapement mechanism at each second magazine having an arm movable in the plane of the bottom second partition strip in the second magazine, and means to oscillate the arm to eject bottom second partition strips at least part way from the second magazine in a direction toward the opposed position, and means to engage the partially ejected second partition strips and move them to the opposed position.

31. A machine for assembling partition strips into inner packs as claimed in claim 30 wherein, the means to engage the partially ejected second partition strips includes a friction wheel and means to drive the friction wheel.

32. A machine for assembling partition strips into inner packs as claimed in claim 31 wherein, the friction wheel is spaced from the horizontal path of movement of the ejected second partition strip, and there are means to press second partition strips into engagement with the friction wheel.

33. A machine for assembling partition strips into inner packs as claimed in claim 32 wherein, there are means to disengage the means to press second partition strips into engagement with the friction wheel after a predetermined operation

of the friction wheel to prevent friction wheel contact with second partition strips which are stationary.

34. A machine for assembling partition strips into inner packs as claimed in claim 33 wherein, the second magazines are in longitudinal alignment with one another and with the opposed position of the second group of partition strips.

35. A machine for assembling partition strips into inner packs as claimed in claim 13 wherein, the source of supply of second partition strips is a plurality of second magazines including a center magazine and end magazines on each side of the center magazine, and the means to gather second partition strips and move them to the position opposed to the assembly position includes means to eject bottom second partition strips from the end magazine and move them to positions beneath the center magazines.

36. A machine for assembling partition strips into inner packs as claimed in claim 35 wherein, the center magazine has an outlet for second partition strips on the plane of the uppermost passage between the table bedplates, and the end magazines have partition strip outlets on the respective planes of the next subjacent passages.

37. A machine for assembling partition strips into inner packs as claimed in claim 36 wherein, the means to move the second group of partition strips into the first group of partition strips includes inserter blades respectively movable in the planes of the gathered second partition strips beneath the center magazine and the plane of the bottom second partition strip in the center magazine.

38. A machine for assembling partition strips into inner packs as claimed in claim 13 wherein, there are means to adjust the machine to accommodate partition strips of different size.

39. A machine for assembling partition strips into inner packs as claimed in claim 13 wherein, there are means to adjust the machine to gather first and second groups of partition strips of different number.

40. A machine for assembling partition strips into inner packs as claimed in claim 13 wherein, there are means to operate the means to move the gathering bar, the means to gather second partition strips and move them to the opposed position, and the means to move the second group of partition strips into the first group, and means to stop the operation of said means at the end of a cycle of operation of each respective means in the event of mispositioning of any partition strip.
